CODED TRACK CIRCUIT SIGNALING
SYSTEMThomas J. Judge, Rochester, N. Y., assignor to
General Railway Signal Company, Rochester,
N. Y.

Application August 24, 1942, Serial No. 455,922

46 Claims. (Cl. 246—3)

This invention relates to coded track circuit signaling systems for railroads, and it more particularly pertains to a system for single track railroads used in connection with centralized traffic control.

According to the general organization of the system provided by the present invention, the automatic control of the signals in accordance with traffic conditions is effected entirely through the track rails by coded track circuit control, the only line wires required being those associated with the communication of controls from a control office to the respective ends of the passing sidings generally known as field stations. Although the apparatus at the field stations can be governed by direct wire control from the control office, it is generally desirable for the purpose of saving line wires that a suitable code communication system be employed as is shown, for example, in the patent to Judge et al., No. 2,082,544, dated June 1, 1937, or in the patent to Hailes et al., No. 2,259,561, dated October 21, 1941.

One object of the present invention is to provide coded track circuits in which driven code pulses are normally transmitted in opposite directions at different intervals through each track section. Such a "driven code" is characterized by having its impulses transmitted in accordance with the intermittent operation of "coding contacts" and also called "oscillator contacts." The invention then provides that the coding contacts normally effective at the opposite ends of each track section (or track circuit) operate at substantially different predetermined rates. This application of code pulses of different rates at the opposite ends of a track section causes the pulses to combine in a manner to effect the intermittent operation of the track relays at both ends of the section in accordance with what has been conveniently termed a "beat code." Although the code following track relay at each end of a section operates as a result of impulses transmitted from the opposite end of the section, such operation is not in exact conformance to the operation of the coding contacts at that other end but is in accordance with a modified or beat code which is used to detect occupancy and provide a tumble-down circuit control as required for a centralized traffic control system for single track railroads.

Such an organization is considerably different than those known in the prior art where a "driven code" is transmitted in one direction through a track section and an "inverse code" is transmitted in the opposite direction through

that track section, because the transmission of an inverse code is wholly dependent upon the reception of the driven code and is transmitted during the "off" periods of such driven code. Thus, 5 in such an organization the cessation of the driven code also causes the cessation of the inverse code, while in the system of the present invention, the stopping of the transmitting means at one end of a track section merely allows the driven code at the other end to be transmitted without interference and received in accordance with the exact rate of its coding contacts then effective.

Also, in such prior systems the driven code in 15 a track section has a rate in accordance with the coding contacts at the transmitting end, while the inverse code takes the same rate as the driven code. But, when the present invention transmits driven codes in opposite directions through 20 a section, the result is beat codes which operate the track relays at both ends of the track section as above mentioned.

Another object of the present invention is to so control the code transmitters at the opposite 25 ends of a track section during normal "beat code" transmission, that the impulses making up the "beat code" are of substantial duration to cause a positive operation of the track relays at both ends of that track section. This is accomplished 30 in accordance with the present invention by controlling each transmitter of a track section so that it cannot interrupt the reception of a pulse from the other end of that track section. Thus, once a transmitter has applied an impulse, such 35 impulse can be terminated only by that transmitter, which provides that the impulses of the "beat codes" are usually of sufficient length to cause the positive response of the code following track relays.

40 In a centralized traffic controlling system for a stretch of single track railroad having signals governing traffic in opposite directions over the stretch, it is necessary that the manual control of a head-block signal governing the entrance of 45 traffic at one end of the stretch shall act to prevent the manual control of the head-block signal governing the entrance of traffic into the other end of the stretch. Thus, a further object of the invention is to so organize the present system 50 that the code transmission through each track section of the single track stretch will be dependent upon the code transmission in the preceding track section for the corresponding direction of code transmission with the manual control of a head-block signal acting to cause the

stopping of the code transmission from its end of the stretch. This cessation of code transmission in each of the track sections for one direction in response to the manual control of a signal obviously prevents code reception at the distant end of the stretch and thus holds the opposing signal at stop, and also acts to prevent manual interruption of the code transmission from such distant end of the stretch. This latter feature is essential so that a manual control for the distant end of the stretch cannot, in any way, interrupt the cleared head-block signal or any cleared intermediate signal if the train has already entered the stretch.

Another object of the present invention is to automatically control the intermediate signals in a stretch of track between passing sidings in such a manner that they can be safely allowed to indicate proceed for the passage of a train in either direction through a stretch of single track after such train has entered the stretch from an outlying track switch located at some intermediate point in the stretch.

Another object of the present invention is to provide indications at the control office as to traffic direction established and as to the presence of trains in various portions of track.

Other objects, purposes and characteristic features of the present invention will be in part obvious from the accompanying drawings and in part pointed out as the description of the invention progresses.

In describing the invention in detail reference will be made to the accompanying drawings in which those parts having similar features and functions are designated throughout the several illustrations by like letter reference characters which are generally made distinctive by reason of preceding numerals indicative of the location of the signal with which such parts are associated and in which:

Fig. 1 illustrates diagrammatically manual control means at a control office for the communication of switch and signal controls to the various field stations, together with means provided at the control office for visually indicating on the control panel the conditions of track occupancy and traffic direction established in various portions of track;

Figs. 2A through 2D when placed side by side respectively illustrate the manner in which coded track circuits are applied to the control of the signals and to the control of traffic direction for this embodiment of the present invention;

Fig. 3 illustrates in detail the manner in which approach locking relays are controlled for the signals at a particular field station;

Fig. 4 illustrates the manner in which approach locking is applied in the power operation of a track switch to provide for its safe operation, together with the control of correspondence relays associated with that track switch;

Fig. 5 illustrates the manner in which the various indications are provided in response to conditions at the respective field stations;

Fig. 6A through Fig. 6K illustrate diagrammatically the conditions of track circuit code transmission for the various track sections under certain typical conditions of train operation;

Fig. 7 illustrates diagrammatically how beat code impulses are formed by the combination of 75 and 120 codes in the form of the invention shown in Figs. 2A-2D.

Fig. 8 shows the trackway of Figs. 2A and 2B

and a portion of their circuits to illustrate a simplified form of the invention.

Fig. 9 illustrates diagrammatically how beat code impulses are formed by the combination of 75 and 120 codes in the form of the invention shown in Fig. 8.

The illustrations employed in the disclosure of this embodiment of the present invention have been arranged to facilitate the disclosure as to the mode of operation and the principles involved rather than for the purpose of illustrating the construction and arrangement of parts that would be employed in practice. Thus, the relays and their contacts are shown in a conventional manner, certain relay contacts being shown in written circuit form and identified as of particular relays by the reference characters appearing directly above such contacts.

The symbols (+) and (-) are employed to indicate the positive and negative terminals respectively of suitable batteries or other sources of direct current, and the circuits with which those symbols are used always have current flowing in the same direction. The symbols (B+) and (B-) indicate connections to the opposite terminals of a suitable battery or other direct current source which has a central or intermediate tap designated as (CN), and the circuits with which those symbols are used may have current flowing in one direction or the other dependent upon the particular terminal used in combination with the intermediate tap (CN).

In order to simplify the description of the present invention, reference is made from time to time to functions common to all parts of a similar character by use in the description of letter reference characters without their preceding numerals for the designation of such parts. It is to be understood that such a reference applies to any parts designated in the drawings by reference characters that are similar except for preceding numerals associated therewith.

The trackway for which this embodiment of the present invention is provided comprises a main stretch of track divided into several track sections and having associated therewith passing sidings A and B (see Figs. 2A through 2D). The right-hand end of the passing siding A is connected to the main track by a track switch 2W, and the left-hand end of the passing siding B is connected to the main track by the track switch 3W. Associated with the track switches 2W and 3W are detector or OS track sections 2-3T and 8-9T respectively. Between the passing sidings A and B are track sections 2-5T, 4-7T, and 6-9T, each of which has coded track circuits. It is to be understood, and it will be readily apparent as the description progresses, that the number of track sections in the stretch of track between the passing sidings A and B can be increased or decreased in accordance with the requirements of practice.

Associated with the right-hand end of the passing siding A are manually controlled signals 2A, 2B, 3A and 3B, signals 2A and 2B being head-block signals governing entrance into the stretch of track between the passing sidings, and signals 3A and 3B being entering signals for governing train movements into the siding section and into the passing siding respectively. In a similar manner signals 8A, 8B, 9A and 9B are associated with the left-hand end of the passing siding B. Intermediate signals 4, 5, 6 and 7 are included in the stretch of track between passing sidings, signals 4 and 6 being provided for governing east-bound traffic (to the right) and signals 5 and

7 being provided for governing westbound traffic (to the left).

Although the signals illustrated in this embodiment of the present invention are of the searchlight type such, for example, as disclosed in the patent to O. S. Field, No. 2,239,316, dated April 22, 1941, it is to be understood that other types of signals such as semaphore signals, position light signals, or signals having individual color lamp units could be employed by slight modification of the circuits disclosed in this embodiment of the present invention in a manner which will readily be recognized by those familiar with the art. The distinctive indications provided by the searchlight signals in this embodiment of the present invention are green indications for clear, yellow indications for caution, and red indications for danger or stop.

Each of the track sections in the stretch of track between the passing sidings A and B, and each of the siding sections 3T and 8-11T has a coded track circuit which includes a code following track relay TR and a source of current at each end of the track section. For the purpose of obtaining the best operating conditions of the code following track relays and certain broken-down insulated joint protection, it is desirable that each track relay TR have a polar structure so arranged as to cause the relay contacts to be biased to a deenergized position from which they can be moved only upon energization of the relay windings with a particular polarity so that current will flow in a direction indicated by arrows in the windings. Each of those track sections also has at each end a code transmitting relay CP which is controlled by suitably selected coding contacts for applying "driven codes" of different rates to the track rails. For purposes of obtaining the high speed operating characteristics for the relays CP, such relays may have polar structures corresponding to that described above for the track relays TR, but this has not been indicated in the drawings.

Suitable code forming devices, or coding contacts, are provided for the respective signal locations for forming the different code rates employed. Although it is to be understood that motor driven coders or other code forming devices could be employed, the codes are formed in this embodiment of the present invention by code oscillators, or coding contacts, which can be of a structure such as is shown, for example, in the application of O. S. Field, Ser. No. 369,862, dated December 12, 1940. An oscillator of such nature is capable of forming but one code, thus requiring separate oscillators for forming the 180, 120 and 75 codes respectively. The system is so organized that each signal location requires an oscillator 180C and either an oscillator 120C or 75C depending upon its relation to other signal locations. In this embodiment, the successive signal locations have oscillators 75C and 120C provided alternately in order that the code oscillators for the opposite ends of each track section will be normally active at substantially different rates for purposes to be hereinafter considered.

Relays H and D controlled through the medium of decoding transformers are provided for the ends of the coded track circuits in the usual manner, each of the H relays being maintained steadily picked up responsive to the pulsing of the associated code following track relay at either code rate, and each of the relays D being picked up

responsive only to the pulsing of the associated code following relay at a 180 rate.

Each of the field stations has office controlled relays for use in the manual control of the track switches and signals, a relay RGZ (see Fig. 2A) being provided for governing the clearing of signals for eastbound traffic, a relay LGZ being provided for governing signals for westbound traffic, a stop relay B being provided for the manual restoration of a signal to stop, a relay WN (see Fig. 4) being provided for governing the power operation of the track switch to its normal position, and a relay WR being provided for governing the power operation of the track switch to its reverse position.

Each of the intermediate track sections has included in its track circuit at each end a series relay SR which follows a code only in response to the presence of a train in that track section, and upon following the code causes the energization of the associated slow acting series repeater relay SRP. At the ends of the stretch of track between passing sidings the relays SRP are used for indication purposes, while the relays SRP at the intermediate signal locations are employed in the control of directional stick relays S, directional stick relay S being provided for each intermediate signal for governing the transmission of codes in the rear of such signal for the control of the signal in the rear under conditions involving the passage of following trains.

Certain of the signals have associated therewith relays YGP which repeat their proceed conditions, light-out relays LO, and relays RGP for repeating the stop or danger conditions of the signals.

Having thus considered the control apparatus employed in this embodiment of the present invention, a consideration will now be given to the mode of operation of the system under various typical operating conditions which would be encountered in practice.

Operation

General.—Before considering in detail the circuit organization provided in accordance with the present invention, brief mention will be made as to the general mode of operation of the system in order to obtain the desired mode of operation without specific reference to the circuits involved.

With reference to Fig. 6A, the normal conditions of track circuit code transmission are illustrated, the direction of the arrows indicating the direction of track circuit code transmission through the respective track sections. From this diagram it will be noted that a 75 code oscillator located at the field station at the right-hand end of the passing siding A governs transmission through the track rails in both directions from that point. At the intermediate signal location having signals 4 and 5, however, a 120 oscillator governs transmission through the track rails in both directions from that point, and in this way the code transmitters for the opposite ends of each of the track sections are normally active as governed by oscillators of substantially different rates. As a result of the transmitters attempting to transmit at different rates for the opposite ends of each of the track sections, beat code impulses are transmitted through the track rails in both directions to energize the track relays at both ends of each track section in the manner later explained.

In accordance with the specific embodiment of

the invention shown, although the transmission of a beat code in each direction through each of the track sections under normal conditions energizes a signal control relay H for each of the intermediate signals, the intermediate signals as well as the manually controlled signals at the field stations are at stop. This is true because each of the intermediate signals can be controlled to a proceed position only if the H relay for governing the opposing signal at that location is deenergized.

According to the diagram of Fig. 6B, conditions are illustrated in which a head-block signal has been cleared for governing passage of an eastbound train into the stretch of track between the passing sidings A and B. Inasmuch as the signal 2B governs passage of a train out of the passing siding A, the conditions of code transmission in the siding section are not changed from their normal conditions, but the manual control of the signal 2B to its proceed position causes the removal of the 75 code normally transmitted from left to right in the track section 2-5T. The removal of such code causes a tumble-down through the remaining track sections in the stretch between passing sidings to provide an interlock for the head-block signals governing entrance to that stretch of track so that the signal 9A or the signal 9B can not be controlled to display a proceed indication for an opposing train movement. Such tumble-down also provides an interlock in the circuits to prevent the removal of the 120 code transmitted from right to left in the track section 6-9T, as the removal of such code by an operator inadvertently attempting to establish an opposing route would cause restoration of the signal 2B to stop in advance of the train.

With reference to Fig. 6C, it will be noted that a manual control has been communicated from the control office for causing the signal 8A to indicate proceed, and such control of that signal has caused the removal of the beat code normally transmitted from right to left in the siding track section 8-11T to establish an opposing signal interlock for purposes just described with respect to the interlock for the opposing signals governing movement of trains in the stretch of track between the passing sidings A and B.

It will be noted in the diagrams of Figs. 6C through 6F that normal conditions of code transmission are restored for the track sections in the rear of an eastbound train, and the restoration of such conditions provides a means for allowing the setting up of a route for a following train by the manual control of the head-block signal 2A or the signal 2B, such control being effective in the same manner as if the entire stretch of track between the passing sidings were unoccupied by a train.

In Fig. 6G it is illustrated how the system provides for the back-up movement of trains in a stretch of track between passing sidings as is often required, for example, as in the movement of a work train. Under the conditions illustrated it is assumed that an eastbound train has proceeded past the intermediate signal 6 so as to allow the track section 4-7T to become unoccupied in the rear of a train and thus allow the restoration of the directional stick relay 4S for the next signal in the rear as illustrated in Fig. 6E. If under these conditions the train desires to reverse its direction of movement, the desired procedure is that the train move across the rail joints past the intermediate signal 7 which would

be at stop under such conditions and send a flagman in the direction of signal 5 to observe the indication of that signal. If it is safe for the train to proceed with its back-up movement, the signal will be at caution as illustrated in Fig. 6G (if the manually controlled signal 3A or 3B at the right-hand end of passing siding A is at stop). If it is unsafe for the train to proceed in its backward movement because of the establishment of a route for a following eastbound train by the control of signal 2A or 2B, the signal 5 will be maintained at stop, and the flagman will not allow the train to proceed with its back-up movement.

With reference to Figs. 6H through 6K it will be noted that the system can be readily adapted to conditions in practice in which outlying track switches are provided at intermediate points between the passing sidings. With reference to Fig. 6H, it has been assumed that the eastbound train has entered the outlying switch 5W to a point beyond fouling position and has restored the track switch to its normal position. Subsequent to the restoration of that switch, the normal conditions of code transmission in the stretch of track are restored, and the return of the train to the main track as illustrated in Fig. 6J causes a tumble-down of the code transmitters in both directions from the track section directly associated with the outlying switch. In accordance with such tumble-down, intermediate signals 5 and 6 are controlled to indicate proceed for train movement in either direction from the track section directly associated with the outlying switch. Such signals will indicate clear of caution in accordance with the conditions of the signals in advance. Thus, in Fig. 6K, the manual control of the signal 3A to a proceed position allows the transmission of a 180 driven code from left to right in the track section 2-5T to provide for the clear indication of signal 5.

Normal conditions.—Under normal beat code conditions, the code transmitter relays CP for the opposite ends of each track section are intermittently energized by their associated coding contacts, but these coding contacts operate at different code rates, such as 75 and 120 times per minute, so that current pulses somewhat variable in duration and spacing are intermittently transmitted in opposite directions at different intervals over the track rails of this track section, and thus intermittently energize the code following track relays TR at both ends of the track section at recurrent intervals to maintain energized an associated code responsive H relay.

Referring to the normal beat code conditions for the track section 2-5T in Figs. 2A and 2B as typical of the other track sections, and considering the preferred organization in which a transmitter relay CP may be energized by closure of its coding contacts only if the associated track relay TR is deenergized, Fig. 7 shows diagrammatically in the form of a time chart the relative timing in the operation of the coding contacts of the oscillators 75C and 120C at the signals 2 and 5 which govern the energization of the transmitter relays 2CP and 5CP respectively, together with the direction and duration of the current pulses in the track rails for this track section and the resultant energization of the track relays 2TR and 5TR at the opposite ends of this track section. In this explanatory diagram or time chart of Fig. 7, the vertical lines on the graphs for the oscillator 75C and 120C indicate opening and closing of the coding con-

tacts during the lapse of time from left to right, and the combined vertical and inclined lines in the graphs for the transmitter relay 2CP and 5CP and the track relays 2TR and 5TR indicate energization or deenergization of these relays, the horizontal lines indicating the time duration of an unchanged condition in the opening or closing of the coding contacts or energization of the relays. With this explanation of the nature of the explanatory diagram of Fig. 7, consideration may now be given to the circuits and operation in detail.

With reference to Fig. 2B, the relay 5CP is normally active to intermittently connect the track relay 5TR and the track battery across the rails of the track section 2-5T, such relay being controlled by the contact of the oscillator 120C. Assuming the relation of the oscillators 120C and 75C for the opposite ends of the track section 2-5T to be as assumed for the first impulses in the diagrams of Fig. 7, the relay 5CP is energized for an "on" period of the oscillator 120C by a circuit extending from (+), including normally closed contacts 104 and 105 of signal 5, contact 52 of oscillator 120C, front contact 53 of relay 4H, front contact 54 of relay 5H, winding of relay 5CP, and back contact 55 of relay 5TR, to (-). The energization of relay 5CP under such conditions is diagrammatically illustrated in Fig. 7 by the dotted line 56. The picking up of the relay 5CP closes a track circuit for the energization of the track relay 2TR at the opposite end of the track section extending from the positive terminal of the track battery 57 including winding of relay 5SR, front contact 58 of relay 5CP, upper rail of track section 2-5T, back contact 59 of relay 2CP (see Fig. 2A), winding of relay 2TR, and lower rail of track section 2-5T, to the negative terminal of track battery 57 (see Fig. 2B). With reference to the diagrams of Fig. 7, the impulse applied to the track circuit by the relay 5CP is terminated by the oscillator 120C as indicated by the dotted line 60. The dropping away of the relay 5CP causes the termination of the impulse in the track rails by the opening of front contact 58 (see Fig. 2B), and as a result of the termination of the impulse, the track relay 2TR (see Fig. 2A) is dropped away. The closure of back contact 61 of relay 2TR causes the energization of the relay 2CP for the transmission of an impulse from left to right in the track section 2-5T as indicated by the dotted line 62 in the diagrams of Fig. 7. Such circuit is closed immediately because of the "on" period formed by the oscillator 75C. The circuit by which relay 2CP (see Fig. 2A) is energized extends from (+), including contact 63 of oscillator 75C, front contact 64 of relay 2H, front contact 65 of relay 2-3TR, front contact 66 of relay 2AS, winding of relay 2CP, and back contact 61 of relay 2TR, to (-).

The picking up of the relay 2CP opens the circuit for relay 2TR at back contact 59 and closes a circuit for the energization of the relay 5TR extending from the positive terminal of track battery 67, including the winding of the relay 2SR, front contact 59 of relay 2CP, upper rail of track section 2-5T, back contact 58 of relay 5CP (see Fig. 2B), winding of relay 5TR, and lower rail of track section 2-5T, to the negative terminal of track battery 67 (see Fig. 2A). It will be noted from the circuit just described that the relay 2CP is maintained picked up for the duration of the "on" period of the oscillator 75C, irrespective of the condition of the oscillator at 75

the opposite end of the track section. This is true because the relay 5CP for the opposite end of the track section can be picked up for the transmission of an impulse only after the track relay

5 TR has been dropped away. Thus, the termination of the "on" period of the oscillator 75C causes the dropping away of the relay 2CP by the opening of contact 63 of oscillator 75C as indicated by the dotted line 68 in the diagrams 10 of Fig. 7, and the dropping away of the relay 2CP terminates the track circuit code impulse and thus causes the dropping away of the relay 5TR (see Fig. 2B). The closure of back contact 55 of relay 5TR closes a circuit by which the relay 5CP can be picked up, because the oscillator 120C is at that time providing an "on" period. Thus, the relay 5CP gains control of the track circuit for the transmission of an impulse by the energization of circuits corresponding to those which have just been described.

Thus, as indicated in the explanatory time chart of Fig. 7, under normal beat code conditions current pulses are transmitted over the track rails of the track section 2-5T in both directions at different intervals, and hence the code following track relays 2TR and 5TR at the opposite ends of this track section are both intermittently energized. In the preferred organization under consideration, these current pulses are transmitted first in one direction and then in the opposite direction alternately as many times per minute as the slower 75 code rate, but the duration and spacing of these current pulses is variable. This is because each transmitter relay 2CP or 5CP is able to apply a current pulse to the track rails upon closure of the associated coding contacts only after the release of the associated track relay 2TR or 5TR upon cessation of the current pulse from the opposite end of the track section. For example, if the coding contacts 120C governing the energization of the transmitter relay 5CP should close during the "off" interval between the current pulses from the opposite end of the track section, then this transmitter relay 5CP is at once energized and is also maintained energized until these coding contacts again open, regardless of the closure of the coding contacts for the opposite end of the track section, so that the resulting pulse is as long as the regular "on" period for the 120 code rate, as indicated in Fig. 7 for the first impulse of the series between the dotted lines 56 and 60. On the other hand, if the coding contacts 120C governing the energization of the transmitter relay 5CP should close at a time when the track relay 5TR is energized by a current pulse coming from the opposite end of the track section, this transmitter relay cannot be energized until such pulse ceases; and this results in shortening or sometimes entirely blanking out the current pulse for that particular closure of the coding contacts 120C, as indicated in Fig. 7 for the second and third operations of the oscillator coding contacts 120C in the series shown.

In other words, as can be seen by a study of the time chart of Fig. 7, in the preferred organization for creating beat code conditions, as contrasted in the alternative form in Figs. 8 and 9 later discussed, the current pulses in opposite directions in the track rails of the track section are not the direct result of the combined operation of coding contacts operating at different code rates of 75 and 120 times per minute; but these current pulses have their duration and spac-

ing modified to a considerable extent by the operation of the track relays for the respective ends of the track section. In such an arrangement, there is no code fight or conflict in the sense that code pulses are applied to the opposite ends of the track section at the same time, and each track battery is connected to the opposite ends of the track section alternately at different intervals and with a periodicity comparable with the slower code rate, thereby providing a duration and spacing of current pulses suitable for operating both code following track relays to maintain a code responsive device energized in substantially the same manner as in response to regularly spaced code impulses at the slower code rate.

The time chart of Fig. 7 merely indicates for purposes of explanation approximate operating times and conditions for certain selected 75 and 120 code rates; and it should be understood that the duration and spacing of the current pulses in opposite directions as shown in this Fig. 7 are merely illustrative or typical of the beat code operation characterizing this invention. In this connection, it can be seen that coding contacts operating independently at different code rates, such as 75 and 120 code rates, will change progressively from a given time relationship with respect to the "on" periods until after a predetermined time interval, this same time relationship again exists. This time interval may be called a beat cycle. For example, as indicated in Fig. 7, if the coding contacts operating at 75 and 120 times per minute open at the same instant, as assumed for Fig. 7, this same relationship recurs after a beat cycle of 4 seconds corresponding with the time required for 5 complete code pulses at the 75 rate and 8 complete pulses at the 120 rate.

Inasmuch as the oscillators for the opposite ends of a track section operate independently of each other, and may happen to start at different instants or perhaps change their exact code rate, there can be other relative time relationships between the "on" periods for 75 and 120 code rates not illustrated in Fig. 7. Generally speaking, the precise duration and spacing of the current pulses and the length of the beat cycle under the beat code conditions contemplated, depend upon the code rates chosen, the relative timing relation of the coding contacts, the accuracy with which each oscillator maintains its particular code rate, and other factors; but the parts of the system can be readily organized to give under such normal beat code conditions a duration and periodicity of current pulses in both directions at intervals suitable for the energization of code responsive means at both ends of the track section for the purpose of detecting occupancy and providing tumble-down control for a system of centralized traffic control for a single track railroad.

At the left-hand end of the track section 2-5T, the pulsing of contact 61 of the relay 2TR (see Fig. 2A) causes the track repeater relay 2TP to follow the beat code being received at that end of the track section. It will be noted that the repeater relay 2TP is employed primarily to lighten the contact load of the track relay 2TR.

The pulsing of contact 69 of relay 2TP energizes the primary winding of the transformer 70 first in one direction and then the other in an obvious manner to induce an alternating voltage in the secondary windings of that trans-

former. The relay 2H is energized under normal conditions by current flowing through its winding in a single direction because of its connection to the center tap of the secondary winding 71 in combination with the use of the rectifying contact 72 of the relay 2TP. The relay 2H is sufficiently slow acting to be maintained steadily picked up when the relay 2TP is active.

At the right-hand end of the track section 10 2-5T the relay 5H (see Fig. 2B) is normally picked up in response to the pulsing of contact 73 of relay 5TP in a manner corresponding to that which has been described for the energization of the relay 2H, except that energy is applied to contact 73 of relay 5TP for the energization of the primary winding of the transformer only in accordance with the closure of back contact 14 of the stick relay 4S associated with the intermediate signal 4. The reason for the inclusion of such contact in the circuit will be hereinafter considered.

The inclusion of a back contact of each track relay TR in the circuit for its associated code transmitting relay CP not only causes more positive operation of the code following track relays 25 at the opposite ends of a track circuit during the beat code transmission in that track circuit, but also provides a check against the energization 30 of the associated home relays H by foreign currents applied to the track rails. This is because the application of a steady foreign current (of a particular polarity if the track relays are polarized as shown) causes the track relays TR at the opposite ends of the track circuit to be steadily picked up, which, of course, causes their associated home relays H to drop away and remain deenergized, but this steady energization of the track relays could not occur if it were not for the back contacts of such track relays included 35 in the circuits for their respective code transmitting relays CP. In other words, the absence of such back contacts would permit the respective transmitting relays CP to cause the coding of their own track relays by energy from the foreign source. This feature of the present invention is to be considered an improvement over a similar check against foreign currents provided in connection with "inverse codes" shown in the prior application of N. D. Preston, Ser. No. 365-50 065, dated November 9, 1940, and no claim is made herein to any subject matter disclosed in such prior application.

It may be noted that the connections to the track rails of the track relays and battery sources 55 are staggered for adjoining track sections so as to give the usual broken-down joint protection.

Having thus considered the manner in which a beat code normally transmitted in both directions through the track section 2-5T is effective 60 to cause the relays 2H and 5H to be picked up, it is to be understood that a similar condition exists under normal conditions for each of the other track sections having a coded track circuit, the energization of the H relays for the intermediate signals being effective only in accordance with the deenergized condition of the opposing stick relays S as described with respect to the control of the relay 5H.

The circuits for the code transmitter relays CP 70 are somewhat different for the intermediate signal locations in order to provide the desired mode of operation for an interlock of the opposing signals. Thus, the code transmitter relays for the intermediate signal locations have their circuits arranged to provide a tumble-down of code

transmission in a particular direction throughout the entire stretch of track between the passing sidings if such tumble-down is initiated by the rendering inactive of the code transmitter at one end of the stretch of track. Generally speaking, the circuit for the code transmitter relay CP at an intermediate signal for transmitting code pulses over the track circuit in the rear of that signal is governed by the signal control relay H for the adjacent end of the adjoining track section in advance of this signal to provide this tumble-down control. More specifically, the relay 4CP (see Fig. 2B) is normally active for transmission of each impulse of a beat code from left to right in the track section 4—7T because of the energization during an "on" period of the oscillator 120C of a circuit extending from (+), including contacts 50 and 51 of the mechanism of signal 4 closed when such mechanism is in its danger position, contact 45 of oscillator 120C, front contact 76 of relay 5H, front contact 77 of relay 4H, winding of relay 4CP, and back contact 78 of relay 4TR, to (—). It will be noted from the circuit just described that the dropping away of the relay 5H because of the relay 2CP being rendered inactive at the left-hand end of the track section 2—5T would cause the relay 4CP to be inactive for the transmission of a code from left to right in the track section 4—7T.

In a similar manner the dropping away of the relay 7H (see Fig. 2C) at the right-hand end of the track section 4—7T upon the rendering of the relay 4CP inactive would open the circuit for the relay 6CP (which corresponds to the circuit just described for relay 4CP) at front contact 79 to stop the transmission of a code from left to right in the track section 6—9T.

The control of the code transmitter relays CP for the ends of a siding section differs primarily in that it is the manual control of the associated signals governing entrance to the sections involved that renders the code transmitters inactive. The relay 8CP (see Fig. 2D), for example, is normally energized for the transmission of each impulse of a beat code by a circuit extending from (+), including contact 80 of oscillator 120C, front contact 81 of relay 8H, front contact 82 of relay 8—9TR, front contact 83 of relay 8AS, winding of relay 8CP, and back contact 84 of relay 8ATR, to (—). It will be hereinafter pointed out specifically how the manual control of the signal 8A to a caution position causes the dropping away of the relay 8AS, and the dropping away of such relay renders the relay 8CP inactive for the transmission of a beat code because of the opening of front contact 83. The code transmitter relay CP for the opposite end of the track section 8—11T is controlled in a similar manner (corresponding to the relay 3CP to Fig. 2A).

The manually controlled signals are all normally at stop and normally dark except for the dwarf signals 2B and 9B governing train movements out of the passing sidings A and B respectively. The intermediate signals are also normally at danger, and normally dark.

The signal mechanisms for the signals at the field stations are normally at stop in accordance with the usual practice in centralized traffic control systems because of the deenergized condition of the office controlled relays LGZ and RGZ associated with the control of the manually controlled signals. The manually controlled signals that are normally dark are dark because of the joint energization of the H relays for the coded

track circuits adjacent that field station, such condition being indicative of a normal condition with no routes established.

The intermediate signals have their signal mechanisms normally at danger because each signal can be cleared only if the H relay for the opposing signal at that location is deenergized. Thus, for example, the mechanism of signal 5 is at stop because the circuit for such signal is open at back contact 85 of the relay 4H for governing the opposing signal 4. The lamps of the intermediate signals are normally dark because of the joint energization of the H relays for the adjacent coded track circuits as has been pointed out with respect to the control of the lamps for certain of the signals at the field stations.

Clearing of a head-block signal.—Assuming the normal conditions to exist as they have been described, and as they are diagrammatically illustrated in Fig. 6A, a typical condition will be described in which it is assumed that an operator desires to establish a route for the passage of an eastbound train out of the passing siding A. Such condition is illustrated in the diagram of Fig. 6B.

To establish such route an operator at the control office actuates the signal control lever 2—3SGL (see Fig. 1) to its right-hand position, and the closure of contact 86 of such lever in its right-hand position applies energy to wire 26 for the energization through a code communication system or by direct wire of the pick-up winding of the relay 2RGZ (see Fig. 2A). If a code communication system is employed, the lower winding of the relay 2RGZ will have a stick circuit to maintain such relay picked up until it is desired to cause the signal to be restored to stop. Such stick circuit can be provided in accordance with the principles of stick signal control, for example, as shown in my prior application, Ser. No. 365,669, dated November 14, 1940.

The picking up of the relay 2RGZ under such conditions closes a circuit for the energization of the mechanism of signal 2B with a polarity to cause such signal to indicate caution (yellow) extending from (+), including front contact 87 of relay 2—3TR, back contact 88 of relay 2D, front contact 89 of relay RGZ, winding of signal 2B, front contact 90 of relay 2RGZ, front contact 91 of relay 2RCR, back contact 92 of relay 2NCR, front contact 93 of relay 2H, and back contact 94 of relay 2D, to (—). It is of course to be understood that the reverse correspondence relay 2RCR is picked up for allowing such signal to indicate proceed only after the track switch 2W has been operated to its reverse position. The track switch 2W can be operated to its reverse position in accordance with the actuation of the switch control lever 2SML (see Fig. 1) to its right-hand position.

60 The positioning of that lever closes a circuit at contact 95 of the lever 2SML in its right-hand position to apply energy to wire 28 for causing the picking up of a relay 2WR (not shown) at field station No. 2. The control of the relay 2WR is provided in a manner similar to that illustrated in Fig. 4 for the corresponding relay 3WR associated with the control of the track switch 3W. The picking up of relay 2WR causes the power operation of the track switch 2W to its reverse position, and when it is in its reverse locked position, the associated correspondence relay 2RCR (corresponding to relay 3RCR) is picked up to close the signal control circuit just described.

In accordance with the operation of the mechanism of the signal 2B to a proceed indicating

position, the relay 2RGP is dropped away by the opening of contact 96 of the signal mechanism, and the dropping of such relay causes the dropping away of the normally energized approach stick relay 2AS by the opening of front contact 97. For the purpose of simplifying the drawings, the control circuit for the relay 2AS is merely indicated by dotted lines as the circuit for such relay corresponds to the circuit illustrated in detail in Fig. 3 for the corresponding relay 9AS associated with the left-hand end of the passing siding B.

When the relay 2AS is dropped away in response to the operation of the mechanism of signal 2B, the relay 2CP is rendered inactive for the transmission of a code in the track section 2-5T by the opening of front contact 66. This initiates a tumble-down which will be effective to render the corresponding code transmitters inactive for the respective track sections included in the stretch of track between the passing sidings A and B.

At the right-hand end of the track section 2-5T, the relays 5TR (see Fig. 2B) and 5TP become inactive because of the inactivity of the code transmitter relay 2CP at the opposite end of the track section, and the relay 5H is dropped away. The dropping away of relay 5H closes obvious circuits for the energization of the signal lamps of signals 4 and 5 at back contact 98, the circuits for the lamps including light-out relays 4LO and 5LO respectively.

The closure of back contact 99 of relay 5H establishes a circuit for the energization of the mechanism of signal 4 with a polarity to cause such signal to indicate caution. Such circuit extends from (+), including back contact 99 of relay 5H, back contact 100 of relay 4D, winding of signal 4, front contact 101 of relay 4H, and back contact 102 of relay 4D, to (-). The conditioning of the mechanism of signal 4 to indicate caution establishes a circuit to cause the picking up of the relay 4YGP extending from (+), including contacts 50 and 51 of the mechanism of signal 4, back contact 103 of relay 5SRP, and winding of relay 4YGP, to (-). The relay 4YGP is sufficiently slow in dropping away to be maintained picked up upon the shifting in the position of the mechanism of signal 4 to change from a yellow to a green indication or vice versa.

Conditions are now established whereby the relay 5CP becomes active for the transmission of a 180 code from right to left in the track section 2-5T. Such circuit extends from (+), including contacts 104 and 105 of the mechanism of signal 5 in its danger position, contact 106 of oscillator 180C, front contact 107 of relay 4LO, front contact 108 of relay 4YGP, back contact 54 of relay 5H, winding of relay 5CP, and back contact 55 of relay 5TR, to (-). It will be noted that back contact 55 of relay 5TR does not alter the pattern of the code transmitted because the relay 5TR remains deenergized.

At the left-hand end of the track section 2-5T, the pulsing of contact 69 of relay 2TP (see Fig. 2A) responsive to the 180 code causes sufficient energy to flow in the tuned circuit for the relay 2D to cause that relay to be steadily picked up. Upon the picking up of the relay 2D, the shifting of contacts 88 and 94 of such relay in the circuit for the control of signal 2B pole changes the winding of such signal in an obvious manner to cause that signal to shift in its position to provide for the display of a clear (green) indication.

A cycle of operation with respect to track circuit code transmission in the track section 4-7T is initiated very similarly to the cycle of operation which has been described with respect to the transmission and reception of track circuit codes in the track section 2-5T, such cycle of operation for the track section 4-7T being initiated when the relay 4CP (see Fig. 2B) is rendered inactive for the transmission of a code upon the dropping away of the relay 5H to open its circuit at front contact 76.

When the relay 4CP becomes inactive for the transmission of a code in track section 4-7T, the relays 7TR (see Fig. 2C) and 7TP at the right-hand end of the track section become inactive, and the cessation of the pulsing of contact 109 of the relay 7TP causes the dropping away of the relay 7H. The dropping away of such relay closes obvious circuits at back contact 110 for the energization of the lamps of signals 6 and 7 and for the energization of the light-out relay 6LO and 7LO. The mechanism of signal 6 is energized upon the dropping away of the relay 7H with a polarity to cause such signal to indicate caution by a circuit extending from (+), including back contact 111 of relay 7H, back contact 112 of relay 6D, winding of signal 6, from contact 113 of relay 6H, and back contact 114 of relay 6D, to (-). The operation of the mechanism of such signal to a position to indicate caution causes the picking up of the relay 6YGP by the energization of a circuit extending from (+), including contacts 115 and 116 of the mechanism of signal 6 in its caution position, back contact 117 of relay 7SRP, and winding of relay 6YGP, to (-). The picking up of relay 6YGP establishes a circuit by which the relay 7CP becomes active for the transmission of a 180 code from right to left through the track rails of track section 4-7T. The relay 7CP is picked up during the "on" periods of the oscillator 180C by the energization of a circuit extending from (+) including contacts 118 and 119 of signal 7 in its danger position, contact 46 of oscillator 180C, front contact 121 of relay 6LO, front contact 122 of relay 6YGP, back contact 123 of relay 7H, winding of relay 7CP, and back contact 124 of relay 7TR, to (-).

The reception at the left-hand end of the track section 4-7T of the 180 code causes the pulsing of contact 125 of relay 4TP (see Fig. 2B) at a rate to effect the picking up of the relay 4D to pole change the circuit for the winding of signal 4 by the shifting of contacts 100 and 102, and thereby cause such signal to display a clear (green) indication.

The relay 6CP (see Fig. 2C) at the left-hand end of the track section 6-9T is rendered inactive by the dropping away of the relay 7H and the opening of its circuit at front contact 79, thus causing the relays 9TR and 9TP (see Fig. 2D) for the right-hand end of the track section 6-9T to become inactive. The cessation of the pulsing of contact 126 of relay 9TP causes the dropping away of the relay 9H, and the dropping away of such relay is effective upon the closure of back contact 127 to energize obvious circuits for the lamps of signals 8A and 9A, such circuits including the light-out relays 8LO and 9LO respectively.

Inasmuch as it has been assumed that no manual control has been communicated to the field station No. 3 for the clearing of a signal at such field station, the dropping away of relay

9H is effective only to establish a new circuit by which the relay 9CP is active for the transmission of a 120 code as selected by the deenergized condition of the relay 8YGP. Such circuit extends from (+), including contact 128 of oscillator 120C, back contact 129 of relay 8YGP, back contact 130 of relay 9H, front contact 131 of relay 8-9TR, front contact 132 of relay 9AS, winding of relay 9CP, and back contact 133 of relay 9TR, to (-). It will be noted that the relay 9CP is active to transmit a 120 code without interference under such conditions, the code transmitter for the left-hand end of the track section 6-9T being inactive. The reception of the 120 code at the left-hand end of the track section 6-9T serves to maintain the relay 6H picked up and the signal 6 at caution because the relay 6D is responsive only to a 180 code.

If an operator has caused the signal 8A at field station No. 3 to indicate proceed, in a manner to be hereinafter considered, the relay 8YGP is picked up, and the energized condition of such relay causes the transmission of a 180 driven code from right to left in the track section 6-9T as indicated in Fig. 6C. Under such conditions the relay 9CP (see Fig. 2D) is active for the transmission of a 180 code by its energization for each "on" period of the oscillator 180C by a circuit extending from (+), including contact 134 of oscillator 180C, front contact 129 of relay 8YGP, back contact 130 of relay 9H, front contact 131 of relay 8-9TR, front contact 132 of relay 9AS, winding of relay 9CP, and back contact 133 of relay 9TR, to (-).

If a 180 driven code is transmitted from right to left in the track section 6-9T, the reception of such code at the left-hand end of the track section causes the energization of the relay 6D (see Fig. 2C), and the picking up of that relay pole changes the circuit for the energization of signal 6 at contacts 112 and 114 to cause such signal to display a clear indication.

It will be noted that the dropping away of the relay 9H at the right-hand end of the track section 6-9T provides an interlock for the opposing signals at the ends of the stretch of track between the passing sidings to prevent an operator from causing the signal 9A or the signal 9B to indicate proceed if he should inadvertently cause the transmission of a manual control from the control office for the proceed indication of either of such signals. In the case of the occupancy of the route by an eastbound train, the interlock not only prevents the proceed indication of an opposing signal, but, in that a proceed indication of such signal is essential in order to render the code transmitter relay 9CP inactive for the transmission of a code in the track section 6-9T, the interlock insures that the relay 9CP will be continuously active to transmit a code in the direction of the eastbound train, independent of any act on the part of an operator at the control office with respect to the transmission of controls to field station No. 3.

Considering the description as it has been set forth for the clearing of the head-block signal 2B for governing train movements out of the siding A, it is believed to be readily apparent to those skilled in the art that a similar mode of operation is effective in the control of the signal 2A associated with train movements from the siding section 3T into the stretch of track between the passing sidings A and B. Thus, if an operator were to cause the clearing of signal 2A, he would operate the switch control lever 2SML (see Fig. 1)

to its normal position, and would operate the signal control lever 2-3SGL to its right-hand position. In accordance therewith, the relay 2RGZ would be picked up in a manner which has been described, and the operation of the track switch 2W to its normal position would cause the energization of relay 2NCR, if such track switch were not already in that position. A circuit would be closed under such conditions for the energization of the mechanism of signal 2A with a polarity to cause such signal to indicate caution extending from (+), including front contact 87 of relay 2-3TR, back contact 88 of relay 2D, front contact 89 of relay 2RGZ, winding of signal 2A, front contact 135 of relay 2RGZ, back contact 136 of relay 2RCR, front contact 92 of relay 2NCR, front contact 93 of relay 2H, and back contact 94 of relay 2D, to (-).

The opening of contact 137 of the mechanism of signal 2A upon the operation of that mechanism to a caution position would cause the dropping away of the relay 2RGZ, and the dropping away of such relay would be effective to render the relay 2CP inactive in a manner which has been described as being effective in response to the operation of the mechanism of signal 2B to a caution position. The rendering inactive of the relay 2CP would be effective to cause a tumble-down of the corresponding code transmitting means for each of the other track sections in the stretch of track between the passing sidings A and B, and the application of a 180 code at the right-hand end of the track section 2-5T would cause the picking up of the relay 2D to pole change the winding of signal 2A by the shifting of contacts 88 and 94 to cause such signal to be operated to a position to provide a clear indication.

Clearing of entering signal.—To consider the control of a signal governing entrance to a siding section, Fig. 2A will be assumed as being placed to the right of Fig. 2D, the circuits of Fig. 2A which have been provided for the right-hand end of the passing siding A corresponding with the circuits which are provided but not specifically shown for the right-hand end of the passing siding B.

For consideration of a typical condition with respect to the clearing of an entering signal, it will be assumed that an operator desires to cause the signal 8A to be cleared for the passage of a train on the main track into the siding section 8-11T. To cause such signal to indicate proceed the operator actuates the lever 8-9SGL (see Fig. 1) to a right-hand position and closes a circuit at contact 138 to apply energy to wire 34 for the communication of a control to the field station No. 3 for energizing the relay 8RGZ (see Fig. 2D). After such relay is picked up, a stick circuit is established in a manner corresponding to that which has been described when considering the control of relay 2RGZ.

The picking up of the relay 8RGZ closes a circuit for the energization of the mechanism of signal 8A with a polarity to cause such signal to assume its caution position. Such circuit extends from (+), including front contact 139 of relay 8-9TR, back contact 140 of relay 8D, front contact 141 of relay 8RGZ, winding of signal 8A, front contact 142 of relay 8RGZ, back contact 143 of relay 3RCR, front contact 144 of relay 3NCR, front contact 145 of relay 8H, and back contact 146 of relay 8D, to (-). It will be noted that although the signal mechanism is energized, the signal is maintained dark unless a route is estab-

lished in the rear of such signal as illustrated in Fig. 6C, or unless there is a train in approach of that signal. If there were a route established as illustrated in Fig. 6C, the relay 9H would be de-energized, and the closure of back contact 127 of such relay would establish obvious circuits for the illumination of the lamps of signals 8A, 8B and 9A, such circuits including the windings of light-out relays 8LO and 9LO respectively.

The dropping away of the relay 8RGP upon the opening of its circuit at contact 147 of mechanism of signal 8A causes the dropping away of the relay 8AS by opening the circuit for such relay at front contact 148 (see Fig. 3 for the complete circuit for relay 8AS). The dropping away of relay 8AS opens the circuit by which the relay 8CP has been normally active for transmission of a beat code at front contact 83 to render the relay 8CP inactive.

When the relay 8CP becomes inactive, the cessation of the pulsing at the right-hand end of the siding section of contact 149 of relay 3TP causes the dropping away of the relay 3H. When the relay 3H is dropped away, the relay 3CP is rendered active to transmit a 75 code (if the relay 2YGP is dropped away). The circuit by which the relay 3CP is active for the transmission of a 75 code extends from (+), including contact 150 of oscillator 75C, back contact 151 of relay 2YGP, back contact 152 of relay 3H, front contact 153 of relay 2-3TR, front contact 154 of relay 3AS, winding of relay 3CP, and back contact 155 of relay 3TR, to (-). It will be noted that the code transmitted is a true 75 code rather than a beat code because of the relay 3TR being steadily de-energized to maintain the back contact 155 closed. The reception at the left-hand end of the siding section of the 75 code maintains the relay 3H picked up, and maintains the conditions which have been described with respect to the caution condition of the signal 8A.

If it is assumed that an operator proceeds to set up a route for an eastbound train so as to cause the clearing of the head-block signal 10A as illustrated in Fig. 6D, the clearing of such signal will cause the picking up of the YGP relay for such signal corresponding to the relay 2YGP illustrated in Fig. 2A, the relay 2YGP being energized when the mechanism of signal 2A is in a proceed position by a circuit extending from (+), including contacts 156 and 157 of signal 2A, front contact 157 of relay 2LO, winding of relay 2YGP, and back contact 158 of relay 3H, to (-). It will be noted that the inclusion of back contact 158 of relay 3H in the circuit for the relay 2YGP checks that the beat code normally transmitted from left to right in the siding section has been removed before the relay 2YGP is allowed to be picked up and to thereby cause an increase in the rate of code transmission in the track section 3T. It will be noted that this increase in rate is accomplished by the shifting of contact 151 of relay 2YGP in the circuit for relay 3CP, the closure of front contact 151 of such relay applying energy through contact 159 of oscillator 180C to a circuit which has been described for the energization of the relay 3CP.

When a 180 code is transmitted from right to left in the track section 8-11T as illustrated in Fig. 6D, the polarity applied to the signal 8A is reversed upon the shifting of contacts 140 and 146 of the relay 8D (see Fig. 2D) to cause such signal to indicate clear (green).

If it were desirable to establish a route for the passage of an eastbound train into the siding

B by controlling the signal 8B to indicate caution, the operator at the control office would actuate the switch control lever 3SML to a reverse operating position to cause the application of energy to the wire 35 for causing the power operation of the track switch 3W.

With reference to Fig. 4, the application of energy to wire 35 causes the picking up of the relay 3WR by the energization of its upper winding and the picking up of such relay causes the release of relay 3WN by opening its stick circuit at back contact 160, the dropping away of relay 3WN establishes a stick circuit for relay 3WR, extending from (+), including back contact 161 of relay 3WN, front contact 160 of relay 3WR, and lower winding of relay 3WR, to (-). In accordance with the picking up of relay 3WR, a reverse operating circuit for the switch machine 3SM is closed at front contact 162, such circuit including normally closed contacts 163 and 164 of the approach locking relays 8AS and 9AS respectively. When the track switch has completed its operation to a reverse position, the relay 3RCR is picked up by the energization of a circuit extending from (+), including front contact 165 of relay 3WR, back contact 166 of relay 3WN, winding of relay 3RCR, contact 167 of relay 3WP in its left-hand position, and front contact 168 of relay 3WP, to (-).

The relay 8RGZ (see Fig. 2D) would be picked up in a manner which has been described if controls were communicated to field station No. 3 for the establishment of a route governing train movement into the passing siding B. The energized condition of the relay 8RGZ, with the track switch 3W operated to its reverse position, would cause the signal 8B to be energized with a polarity to operate its mechanism to a caution position. Such circuit extends from (+), including front contact 169 of relay 8RGZ, winding of signal 8B, front contact 170 of relay 8RGZ, front contact 171 of relay 3RCR, back contact 172 of relay 3NCR, and front contact 173 of relay 8-9TR, to (-).

It will be noted that although the operation of the mechanism of signal 8B to a caution position would cause the dropping away of relay 8RGP by the opening of its circuit at contact 174, and the dropping away of relay 8RGP would cause the dropping away of relay 8AS by the opening of its circuit at front contact 148, the code transmitter relay 8CP would not be rendered inactive because of the closure of front contact 175 of the correspondence relay 3RCR to shunt contacts 82 and 83 of relays 8-9TR and 8AS out of the circuit by which the relay 8CP is normally active. Thus, the control of signal 8 for the passage of a train into the passing siding B has no effect upon the beat code normally transmitted in the siding section 8-11T, therefore allowing the establishment of a route for an opposing train through the siding section as is often desirable upon the meeting of trains.

Passage of a train.—With reference to Figs. 6B through 6F, typical conditions will be considered with respect to the passage of an eastbound train from the passing siding A to the passing siding B.

With reference to Figs. 6B and 6C, it will be assumed that the eastbound train accepts the head-block signal 2B which has been allowed to clear in a manner which has been described and has entered the end section 2-5T in the stretch of track between the passing sidings A and B. The passage of the train into the detector track

section 2—3T causes the dropping away of the relay 2RGZ (see Fig. 2A) by the opening of the stick circuit for such relay in accordance with usual practice in the control of stick signals (not shown). It is to be understood, however, that non-stick signals can be used in accordance with the requirements of practice. The closure of back contact 90 of relay 2RGZ shunts the winding of signal 2B in an obvious manner to cause such signal to be put to stop. When the signal is restored to stop, the stop repeater relay 2RGP is picked up by the energization of a circuit extending from (+), including contacts 156 and 137 of signal 2A in its stop position, contacts 96 and 176 of signal 2B in its stop position, and winding of relay 2RGP, to (—). The closure of front contact 97 of relay 2RGP with the OS track section 2—3T occupied by the train establishes a pick-up circuit for the relay 2AS corresponding to a pick-up circuit provided under similar conditions for the relay 9AS as illustrated in detail in Fig. 3. It will be noted that the picking up of the relay 2AS cannot render the relay 2CP active for the transmission of a code in the track section 2—5T while the OS section is occupied because the circuit for such relay is open at front contact 65 of the relay 2—3TR.

When the detector track station 2—3T becomes unoccupied in the rear of the eastbound train, the relay 2CP becomes active for the transmission of a 75 code in the track section 2—5T in the rear of the train as indicated in Fig. 6C. The circuit by which the relay 2CP is active for the transmission of such code corresponds to that which has been described when considering the normal conditions of the system. It will be noted that the relay 2CP applies a true 75 code under such conditions because the back contact 61 of relay 2TR is maintained steadily closed.

The presence of the train in the approach of signal 4 causes sufficient current to flow in the track circuit for track section 2—5T to render the series relay 5SR (see Fig. 2B) active, and in accordance with the pulsing of contact 171 of relay 5SR, the slow acting repeater relay 5SRP is picked up and maintained in a picked up position.

The picking up of relay 5SRP closes a pick-up circuit for the directional stick relay 4S extending from (+), including contacts 59 and 51 of signal 4 in its clear position, front contact 103 of relay 5SRP, front contact 178 of relay 4YGP, and winding of relay 4S, to (—). The picking up of that relay closes a stick circuit at front contact 179 for shunting front contact 178 of relay 4YGP out of the circuit just described. The relay 4YGP is deenergized upon the picking up of relay 5SRP by the opening of back contact 103, but it is sufficiently slow in dropping away to allow time to insure the picking up of the stick relay 4S. The dropping away of the relay 4YGP opens the pick-up circuit for the relay 4S at front contact 178, and closes a stick circuit to maintain the relay 4S picked up extending from (+), including back contact 178 of relay 4YGP, front contact 179 of relay 4S, and winding of relay 4S, to (—). It will be noted that by this circuit organization the stick relay 4S is picked up when an eastbound train is in approach of signal 4, rather than being dependent upon a straddle joint type system of energization which is often faulty in its operation upon the passage of short trains.

With the relay 4S picked up and the relay 4YGP dropped away, the relay 5CP becomes ac-

tive for the transmission of a 120 code because of the energization for each "on" period of the oscillator 120C of a circuit extending from (+), including contacts 104 and 105 of signal 5 in its danger position, contact 52 of oscillator 120C, front contact 180 of relay 4S, back contact 108 of relay 4YGP, back contact 54 of relay 5H, winding of relay 5CP, and back contact 55 of relay 5TR, to (—). The transmission of such 120 code in track section 2—5T conditions the system so that a signal 2A or 2B may be manually cleared for a following train when the track section 2—5T becomes unoccupied by the train under consideration. This is true because the normal conditions of beat code transmission becomes effective in the track section 2—5T when such section becomes unoccupied in the rear of an eastbound train as illustrated in Fig. 6D, thus conditioning the system so that the signal 2A or 2B can be controlled if desired to establish a route for a following train. The normal conditions of the code transmission become effective in the track section 2—5T when such section becomes unoccupied in the rear of a train because the code transmitters for the opposite ends of the track section are both active at that time.

It will be noted that the relay 4YGP is dropped away in connection with the control of the stick relay 4S prior to the restoration of signal 4 to danger. Such signal is operated to its danger position when the eastbound train enters the track section 4—7T, and by shunting such section causes the dropping away of relay 4H. The dropping away of that relay opens the circuit for signal 4 at front contact 101.

When the eastbound train occupies the track section 4—7T as illustrated in Fig. 6D, and the track section 2—5T has become unoccupied in the rear of the train, although a beat code is transmitted from left to right in the track section 2—5T, the relay 5H (see Fig. 2C) is maintained dropped away because of the inclusion in its circuit of back contact 74 of the stick relay 4S. Thus, the opposing intermediate signal 5 is maintained at danger even though the block in advance thereof is unoccupied by a train. This is in accordance with the desired mode of operation for governing the passage of trains making back-up movements. Such train movements will hereinafter be more fully described.

The presence of the eastbound train in the track section 4—7T causes the series relay 7SR to be active, and to effect the picking up of the directional stick relay 6S by the energization of circuits corresponding to those which have been described in detail with respect to the control of the relay 4S. The picking up of the relay 6S causes the relay 7CP to be active for the transmission of a 75 code by the energization of a circuit corresponding to that which has been described by which the relay 5CP has been active for the transmission of a 120 code in accordance with the energized condition of the relay 4S.

As the eastbound train proceeds further so as to cause the track section 4—7T to become unoccupied in the rear of the train, as illustrated in Fig. 6E, the 120 code transmitted from right to left in the track section 4—7T causes the picking up of the relay 4H (see Fig. 2B). The picking up of such relay with the relay 4D deenergized closes a circuit for the energization of the mechanism of signal 4 with a polarity to cause such signal to indicate caution. Such circuit extends from (+), including back contact 99 of

relay 5H, back contact 100 of relay 4D, winding of the mechanism of signal 4, front contact 101 of relay 4H, and back contact 102 of relay 4D, to (-). The operation of the mechanism of signal 4 to a caution position causes the picking up of relay 4YGP because the series repeater relay 5SRP has been dropped away when the track section 2-5T has become unoccupied in the rear of a train. The picking up of relay 4YGP opens the stick circuit which has been described for relay 4S at back contact 178 to cause that relay to be dropped away.

Upon the dropping away of the relay 4S, the circuit to allow the energization of the relay 5H is closed at back contact 74, and the picking up of relay 5H in accordance with the reception of a beat code in the track section 2-5T opens the circuit which has been described for the mechanism of signal 4 at back contact 99, to cause the mechanism of that signal to be restored to danger. In accordance with the restoration of signal 4 to danger, the relay 4YGP is dropped away by the opening of its circuit at contact 51 of the mechanism of signal 4.

Upon reviewing the mode of operation just described, it will be noted that the signal 4 has been momentarily energized to indicate caution when the track section 4-7T has become unoccupied in the rear of the eastbound train, and such momentary energization has served to cause the release of the directional stick relay 4S, the release of such relay being effective to cause the picking up of the relay 5H for the track section in the rear of signal 4. The picking up of relay 5H has in turn opened the circuit for the control of signal 4 to complete the restoration of signal 4 to its normal danger condition.

When the relay 5H is picked up, a circuit is established for the relay 5CP by which such relay is normally active for the transmission of a beat code in accordance with the energized condition of the relays 5H and 4H as has been described when considering the normal conditions of the system.

Similarly, the joint energization of the relays 5H and 4H closes a circuit by which the relay 4CP becomes active for the transmission of a beat code in the track section 4-7T in the direction of signal 7. Such relay cannot become active, however, until the mechanism of signal 4 has been restored to its danger condition as energy for that relay checks the mechanism of signal 4 at danger.

The reception at the right-hand end of track section 4-7T of the beat code transmitted from the opposite end of that track section cannot be effective to cause the relay 7H to be picked up, because of the energized condition of the relay 6S to open the circuit for relay 7H at back contact 181.

To consider further progress of the eastbound train, it will be assumed that the signal 8A has been controlled to display a clear indication for the passage of the train through the siding section 8-11T on the main track. The acceptance of such signal by the train causes the dropping away of the relay 8RGZ in a manner corresponding to that described with respect to the passage of the train past the signal 2B. In accordance with the restoration of such signal to stop, the relays 8RGZ and 8AS are picked up, and when the detector track section 8-9T becomes unoccupied in the rear of the train, the picking up of relay 8-9TR closes a circuit by which the relay 8CP becomes active for the transmission of

a 120 code in the section 8-11T in the rear of the train. Such circuit extends from (+), including contact 80 of oscillator 120C, back contact 182 of relay 9YGP, back contact 81 of relay 8H, front contact 82 of relay 8-9TR, front contact 83 of relay 8AS, winding of relay 8CP, and back contact 84 of relay 8TR, to (-).

When the detector track section 8-9T becomes unoccupied in the rear of a train, the relay 9CP also becomes active for the transmission of a 120 code from right to left in the track section 6-9T. The relay 9CP is energized, during "on" periods of the oscillator 120C under such conditions by a circuit extending from (+), including contact 128 of oscillator 120C, back contact 129 of relay 8YGP, back contact 130 of relay 9H, front contact 131 of relay 8-9TR, front contact 132 of relay 9AS, winding of relay 9CP, and back contact 133 of relay 9TR, to (-).

The reception at the left-hand end of the track section 6-9T of the 120 code causes the picking up of relay 6H, and the picking up of such relay is effective to momentarily operate the mechanism of signal 6 to a caution position in order to provide for the release of the stick relay 6S in a manner corresponding to that which has been described for the release of the relay 4S. In accordance with the dropping away of relay 6S, the closure of back contact 181 allows the picking up of relay 7H, and the picking up of such relay establishes a circuit by which the relay 6CP is effective to transmit a beat code in the track section 6-9T. The relay 6CP is picked up for each impulse of that code by the energization of a circuit which has been described when considering the normal conditions of the system. When the relay 6CP becomes active for the transmission of a code, the normal conditions are established whereby the relay 9CP is active for the transmission of a beat code at the same time in the track section 6-9T.

To consider the conditions of restoration to normal for code transmission in the siding section, it will be assumed that a route is established for further passage of the eastbound train by the clearing of signal 10A (see Fig. 6F). Upon the acceptance of such signal by the train, and when the detector section 10-11T becomes unoccupied in the rear of the train, the code transmitter relay corresponding to relay 3CP of Fig. 2A becomes active for the transmission of a beat code in the siding section. The circuit by which the relay 3CP would be active under similar conditions extends from (+), including contact 150 of oscillator 75C, front contact 152 of relay 3H, front contact 153 of relay 2-3TR, front contact 154 of relay 3AS, winding of relay 3CP, and back contact 155 of relay 3TR, to (-). It will be noted that the relay 3H is picked up at that time because of the 120 code which has been described as being applied at the left-hand end of the siding section 8-11T to follow the train through the section. Thus, as soon as the detector section 10-11T becomes unoccupied in the rear of the eastbound train the normal conditions of beat code are established in the siding section as illustrated in Fig. 6A.

Following train movements.—It has been pointed out heretofore in the description that the presence of a beat code in the coded track circuit in advance of a signal subject to manual control is a condition which allows such signal to be controlled to display a caution indication. Thus, by the restoration of a beat code for each

of the coded track circuits which becomes unoccupied in the rear of a train, it is provided that a route can be established for a following train, the establishment of such route being accomplished in a manner very similar to that which has been described for the establishment of a corresponding route for a first train.

With reference to Fig. 6D, for example, it will be noted that the presence of the beat code in the track section 2-5T allows the signal 2A or the signal 2B to be cleared responsive to a manual control communicated from the control office for the clearing of either of such signals in accordance with the energized condition of the relay 2H (see Fig. 2A) for the left-hand end of the track section 2-5T. Inasmuch as the track section 4-7T is occupied by the first train, the deenergized condition of the relay 4YGP (see Fig. 2B) is effective by the closure of back contact 168 to render the relay 5CP active for the transmission of a 120 rather than a 180 code. Thus, the picking up of the relay 2RGZ (see Fig. 2A) for either of such head-block signals 2A or 2B would cause that signal to indicate caution in accordance with the reception of a 120 code transmitted from the right-hand end of the track section 2-5T. The code received at the left-hand end of the track section 2-5T would be a true 120 code rather than a beat code, because the code transmitter relay 2CP would be rendered inactive under such conditions by the dropping away of relay 2AS in a manner which has been described.

If the first train were further in advance of the signal to be cleared for a following train as illustrated in Fig. 6E, the conditions would be effective as they have been described for the clearing of signal 2B when the trackway in advance of such signal is unoccupied by a train. This is true because the presence of the code in the track section 4-7T in the rear of the first train is effective to restore the stick relay 4S and to cause the transmission of a 180 code from right to left in the track section 2-5T in accordance with the energization of relay 4YGP. Signal 4 would indicate caution under such conditions in accordance with the transmission of a 75 code from right to left in the track section 4-7T.

Another desirable characteristic of the present invention with respect to the passage of following trains is that the communication of a control for the clearing of a head-block signal, for example, for a following train at a time when the first train is not sufficiently in advance to allow the head-block signal to indicate proceed, is effective to cause such signal to indicate proceed when the track section having a coded track circuit in advance of such signal becomes unoccupied in the rear of the first train. In other words, the manual control communicated from the control office is not lost if the signal desired to be controlled cannot be operated to a proceed position at the time the manual control is communicated. This is true because the office controlled relay such as the relay 2RGZ is maintained picked up by a local stick circuit which is preferably arranged by a combination of front and back contacts of the detector track relay and its repeater relay respectively to provide for a momentary interruption in the stick circuit for the release of the relay only upon the entrance of a train into the detector section involved, in the manner disclosed in my prior application Ser. No. 365,669, filed November 14, 1940.

Thus, if a train is occupying the track section 2-5T as illustrated in Fig. 6C at the time when a manual control is communicated from the control office for governing the signal 2A for the establishment of a route for the following train, the relay 2H (see Fig. 2A) is dropped away, and the deenergized condition of such relay prevents the energization of the mechanism of signal 2A by the opening of its circuit at front contact 93. However, when the first train advances to a position to cause the track section 2-5T to become unoccupied in the rear of the train, a code is transmitted from right to left in the track section 2-5T to cause the picking up of the relay 2H, and in accordance therewith, the signal 2A or the signal 2B (whichever has been manually selected) is controlled to a caution indicating position. It will be noted that the condition just described by which a control communicated from the control office is not lost if the signal desired to be controlled cannot indicate proceed immediately is also applicable to other traffic conditions affecting the control of the signal involved. Such a condition, for example, could be created in accordance with the establishment of routes for switching train movements at the next passing siding.

Back-up train movements.—It is often desirable, particularly with respect to train movements involving work trains, to reverse the direction of train movement in the stretch of track between the passing sidings; but, in accordance with the principles of APB involving the use of directional stick relays S, back-up train movements should be allowed only in accordance with certain prescribed flagging protection as established by railroad practice. Such protection is primarily required upon passage of a train through the first block in its back-up train movements, as the directional stick relays S for the more distant signal locations have been restored due to the initial train movement.

With reference to Fig. 6G, a condition is diagrammatically illustrated involving a back-up train movement. The condition assumed is that an eastbound train has proceeded to a position as illustrated in Fig. 6E to have allowed the track section 4-7T to become unoccupied in the rear of the train and thus provide for the dropping away of the stick relay 4S. If it is desired that such train reverse its direction, in accordance with instructions issued by the dispatcher for the eastbound train to reverse its direction and proceed toward the passing siding A, it is required that such train will send a flagman ahead to provide flagging protection before backing past the signal 7 then at stop across the rail joints into the track section 4-7T, and the flagman will go far enough in the direction of the intermediate signal 5 to observe its indication. If the signal 5 indicates caution, as illustrated in Fig. 6G, it is safe for the train to proceed under signal indications in the direction of the passing siding A, such train being governed by proceed indications if the trackway is unoccupied, irrespective of the number of intermediate signal locations included in the trackway before reaching the next passing siding.

Such mode of operation is effective because the backward movement of the train so as to occupy the track section 4-7T causes a tumble-down in the track sections to render the code transmitters associated with the right-hand end of the track sections between that train and the next passing siding inactive. In accordance with the

inactivity of such transmitters, opposing signal protection is provided, and the opposing head-block signals at the next passing siding cannot be controlled to a proceed position for governing an opposing train. It is further provided, that the inadvertent attempt of an operator to clear one of such signals cannot disturb the code transmitted through the various track sections in the direction of the train making the back-up movement. This is because the removal of such code is dependent upon a proceed indication of one of the head-block signals.

It will be noted that the removal of the code normally transmitted from right to left in the various track sections between the train making the back-up movement and the next passing siding allows the transmission of codes from left to right in the track sections without interference of the transmitters at the opposite ends of such sections.

It is believed that it will be readily apparent that a back-up train movement can be further facilitated if desired by the communication of a control from the control office for governing the proceed indication of signal 3A, if it is desired that the train making the back-up movement proceed into the siding section 3T. The control of the signal 3A to a caution position under such conditions would cause the code transmitter relay 2CP to become active to transmit a 180 code rather than a 75 code in the track section 2-5T for the control of signal 5 in accordance with the closure of front contact 183 of relay 3YGP (see Fig. 2A). The reception of such code at the right-hand end of the track section 2-5T would cause the signal 5 (see Fig. 2B) to indicate clear rather than caution because of the energization of relay 5D to pole change the circuit for signal 5 at contacts 184 and 186. It is believed to be readily apparent that the normal conditions of beat code transmission would be established for the track sections which become unoccupied as the train proceeds in making its back-up movement in a manner corresponding to the restoration to normal conditions in the rear of a train proceeding steadily in a given direction. The stick relay 6S is restored when the track section 4-7T becomes unoccupied so as to cause the dropping away of relay 1SRP (see Fig. 2C).

Outlying switch.—Conditions are often encountered in practice where an outlying switch is associated with one of the intermediate track sections in a stretch of track between passing sidings, such outlying switch being, for example, for a spur track or the like. Under most conditions the outlying switch is hand operated, and there are no special signals provided for governing train movement over the switch. In such cases, train movements are governed entirely by the usual automatic intermediate signals in combination with instructions from the dispatcher at the control office.

It is to be understood that the present system is readily adaptable without modification of the circuits to conditions in which outlying switches are associated with the intermediate track sections. Although several outlying switches can be associated with the stretch of track between two passing sidings, for the purpose of illustrating how the present invention can be applied to outlying switches, it will be assumed that an outlying switch 5W is associated with the track section 4-7T as indicated by the dotted lines of Fig. 2B, and as indicated in the diagrams of Figs. 6H through 6K. It is to be understood that such

track switch can be included or not, without modification of the circuits.

With reference to the diagrams of Figs. 6H through 6K, a traffic condition has been illustrated in which it is assumed that an eastbound train has entered the turnout track X connected by the outlying switch 5W to the main track to leave some cars or for other purposes, and it is assumed that such train subsequently proceeds 10 in one direction or the other from the outlying switch to the passing siding A or the passing siding B.

With reference to Fig. 6H, it is assumed that the eastbound train has entered the outlying switch 15 5W beyond the fouling position of the switch and a trainman has restored the track switch 5W to its normal position. In accordance with the restoration of the switch to normal, the shunt ordinarily applied by the track switch in 20 its reverse position across the track rails of the track section 4-7T is removed, and the removal of such shunt allows the restoration to normal conditions of beat code transmission in the various track sections in the stretch of track in a manner very similar to the manner in which restoration 25 is effective upon continued progress of an eastbound train through the stretch.

When the train is ready to proceed again on the main track, after having received permission 30 from the dispatcher to enter such track, a trainman reverses the track switch 5W, and the shunting of the rails causes the dropping away of the relays 4H and 7H for the ends of the track section 4-7T.

35 The dropping away of the relay 4H (see Fig. 2B) opens the circuit by which the relay 5CP is normally active at front contact 53, and with the stick relay 4S dropped away, the relay 5CP becomes inactive for the transmission of a code in 40 the track section 2-5T. At the left-hand end of the track section 2-5T, the dropping away of relay 2H (see Fig. 2A) establishes a circuit by which the relay 2CP is active for the transmission of a 75 code. Such circuit extends from (+), including contact 63 of oscillator 15C, back contact 45 183 of relay 3YGP, back contact 64 of relay 2H, front contact 65 of relay 2-3TR, front contact 66 of relay 2AS, winding of relay 2CP, and back contact 61 of relay 2TR, to (-). It will be noted 50 that the deenergized condition of the relay 2H provides an opposing signal interlock as described above when considering back-up train movements to prevent either signal 2A or signal 2B from indicating proceed in response to the inadvertent 55 communication of a manual control for either of such signal from the control office.

In accordance with the reception at signal 5 of the 75 code transmitted in the track section 2-5T, the mechanism of such signal is energized 60 with a polarity to cause its operation to a caution position. Such energization is in accordance with the deenergized condition of the relay 4H (see Fig. 2B), the circuit extending from (+), including back contact 85 of relay 4H, back contact 184 of relay 5D, winding of signal 5, front contact 185 of relay 5H, and back contact 186 of relay 5D, to (-). It will be noted that the lamps of signals 4 and 5 are energized because of their circuits being closed at back contact 187 of relay 4H.

65 Inasmuch as the circuit organization of the system is symmetrical for similar conditions affecting opposite directions of traffic, conditions corresponding to those described are established for eastbound traffic to provide for the caution 70 indication of the intermediate signal 6, such sig-

nal being at caution in accordance with the de-energized condition of the relay 7H (see Fig. 2C) when a 120 code is transmitted in the track section 6—9T for the energization of the relay 6H. The circuit for the relay 6CP is open at front contact 79 of relay 7H to render that relay inactive, and thus provide an opposing signal interlock to prevent the control of signal 9A or signal 9B to a proceed position.

From the description as it has been set forth it is believed to be readily apparent that a greater number of intermediate signals could be involved in governing the passage of a train from an out-lying switch, if the stretch of track between the passing sidings were long enough to require the addition of such signals. Where more signals than those illustrated are involved, the signals governing movement of the train (other than the first signal encountered) can indicate clear or caution in accordance with the proceed or danger indication of the next signal in advance. This being true, more favorable signal indications can be provided by an operator allowing an entering signal, such as the signal 3A to indicate proceed. Under such conditions, the energization of the relay 3YGP (see Fig. 2A) would be effective upon the closure of front contact 183 to cause the relay 2CP to be active for the transmission of a 180 code as applied by contact 183 of oscillator 180C. The reception of the 180 code at the right-hand end of track section 2—5T would cause the relay 5D (see Fig. 2B) to be picked up to pole change, the circuit for signal 5 at contacts 184 and 186 to cause such signal to indicate clear.

Approach locking.—Approach locking is provided at each of the field stations by the use of approach locking relays AS associated with the signals in a manner very similar to that commonly employed in practice, the approach control of the relays AS being arranged to conform to the coded track circuit system of the present invention. To simplify the drawings and description, only the approach locking circuits associated with the field station No. 3 are considered in detail as it is to be understood that such circuits are typical of the approach locking circuits provided at each of the other field stations.

With reference to Fig. 3, the relay 8AS is provided for the signals 8A and 8B for eastbound traffic, and a relay 9AS is provided for signals 9A and 9B for westbound traffic. Each of the AS relays is normally maintained energized by its stick circuit corresponding to the circuit for relay 8AS extending from (+), including front contact 148 of relay 8RGP, winding of the thermal relay 8TH, front contact 189 of relay 8AS, and winding of relay 8AS, to (—). The resistance of the winding of the relay 8AS is sufficient to render the thermal relay 8TH normally ineffective. It will be noted from the circuit just described that the relay 8AS is dropped away when either signal 8A or 8B is operated to a proceed position to cause the opening of the circuit for that relay at front contact 148 of relay 8RGP. The manual restoration of either of such signals to stop (as can be effected by the picking up of the relay 8—9B through the code communication system in a manner more fully disclosed in my prior application, Ser. No. 365,669, dated November 14, 1940) is effective to start the timing of the thermal relay 8TH by the energization of a circuit extending from (+), including front contact 148 of relay 8RGP, winding of the thermal relay 8TH, and back contact 189 of relay 8AS, to (—). If the normal conditions of the system exist, however, with respect to the transmission of beat codes in

the track section 6—9T so as to cause the relay 9H to be picked up, the front contact 190 of relay 9H serves as an approach release contact to allow the immediate picking up of the relay 8AS. The relay 8AS can be picked up under such conditions by a circuit extending from (+), including front contact 148 of relay 8RGP, front contact 190 of relay 9H, and winding of relay 8AS, to (—). It will be noted that the relay 9H would be dropped away if an eastbound train were in the stretch of track between the passing sidings A and B, or if a tumble-down has been effected by the manual control of signal 2A or signal 2B to a proceed indicating position. Under such conditions, it is required that the thermal relay 8TH complete its operation to close contact 191 in order to provide for the picking up of relay 8AS.

Upon passage of a train past the signals 8A and 8B, the relay 8AS is restored without the operation of the thermal relay 8TH in the usual manner. According to the circuits illustrated in Fig. 3, the relay 8AS is restored upon passage of a train in accordance with the closure of back contact 192 of the OS track relay 8—9TR, but it is to be understood that restoration can be rendered effective dependent upon back contacts of relays 8—9TR and 8H connected in series for train movements over the track switch 3W in its normal position if such type of restoration is required in practice. This type of restoration is sometimes desirable for protection against faulty operation by a section man dropping a bar across the rails or the like.

It is believed to be readily apparent that a similar mode of operation is effective for the control of the relay 9AS associated with the signals 9A and 9B, except that the front contact 193 of relay 8H can be effective in the approach release pickup circuit for the relay 9AS only when the track switch 3W is in its normal position as selected by front contact 194 of relay 3NCR included in series with the relay 8H in the approach release circuit for relay 9AS. Such arrangement provides that there is no approach release provided when the signal 9B for governing train movements out of the passing siding is manually restored to stop, the operation of the thermal relay 9TH being required under such conditions irrespective of whether or not there is a train in approach of the signal 9B.

It has been pointed out that the approach locking relays AS have front contacts included in the switch operating circuits for the associated track switches, and also in the circuits by which the code transmitter relays are normally active at the associated field stations. More specifically, contacts 163 and 164 of relays 8AS and 9AS respectively are included in the control circuit for the switch machine 3SM at field station No. 3, and the relays 8AS and 9AS have front contacts 83 and 132 (see Fig. 2D) respectively included in the circuits by which the relays 8CP and 9CP are normally active. By this arrangement, for example, the manual restoration of the head-block signal 9A to stop, allows the restoration of the relay 9AS, only after the thermal relay 9TH associated with the relay 9AS has completed its operation, provided the approach release circuit for the relay 9AS cannot be closed because of the deenergized condition of relay 8H. Under such conditions the relay 9CP cannot become active until the end of a predetermined time interval after the restoration to stop of the signal 9A, and the delay in the restoration of the relay 9CP causes a delay in the clearing of the opposing

head-block signal 2A or 2B at the passing siding A, if a control is communicated from the control office for causing either of such signals to indicate proceed. This mode of operation is in accordance with the principles of time and approach locking in that a time period is provided during which a train can overrun the signal which has been restored to stop, and thereby provide an opposing signal interlock through the track rails extending to the opposing head-block signals at the next passing siding.

Approach lighting.—Approach lighting is provided for each of the signals, except for the dwarf signals governing train movements out of the passing sidings. Such dwarf signals are not generally provided with approach lighting because the trackway of the passing sidings generally has no track circuits. Each of the other signals, however, has its signal lamp illuminated whenever the relay H for either adjacent coded track circuit is deenergized. From the mode of operation as it has been described, it will be noted that the H relays for both adjacent coded track circuits at each of the signal locations are energized contemporaneously under normal conditions. Thus, when a route is established, such for example, as a route extending from the signal 2A to the signal 8A, the tumble-down of the opposing H relays is effective to illuminate the signal lamps for the signals involved in that stretch of track for governing traffic in both directions. Such tumble-down is also effective to cause the illumination of the lamps of the signals at the field stations at the opposite ends of the stretch of track. A similar mode of operation is effective when a route is established through a siding section such as the section 8—11T. As the beat code is restored for the various track sections in the rear of a train, the signal lamps are extinguished for the various signal locations when the H relays are restored to their normally energized conditions for the coded track circuits terminating at such signal locations. More specifically, for example, the lamps of signal 5 and signal 4 are extinguished when an eastbound train has proceeded to the position as indicated in Fig. 6E to cause the track section 4—7T to become unoccupied in the rear of the train. The lamps of those signals are extinguished by the opening of back contacts 187 and 98 of relays 4H and 5H (see Fig. 2B) respectively.

Light-out protection.—At various points in the description it has been described that light-out relays LO are included in the circuits for the lamps of certain of the signals, a light-out relay LO being included in the circuit for the lamp of each signal, except the dwarf signals for governing train movements into and out of the passing sidings. The purpose of each of the light-out relays is to allow the transmission of a 180 code in the rear of the associated signal in accordance with the energized condition of the relay YGP for such signal, only if the signal lamp for that signal is illuminated. In other words, the failure of a signal lamp to be illuminated is considered as a danger signal, and therefore the next signal in the rear should be allowed to display a signal indication no more favorable than a caution indication.

For example, if the lamp of signal 8A is burned out, but the mechanism of such signal is conditioned for a proceed indication, the deenergized condition of the light-out relay 8LO (see Fig. 2D) is effective to prevent the energization of the relay 8YGP, and the failure of relay 8YGP to be

5 picked up selects a 120 rather than a 180 code for transmission to the next signal in the rear through the rails of the track section 6—9T by the closure of back contact 129 in the circuit for the control of the relay 9CP.

10 In a similar manner, for each of the intermediate signals, the deenergized condition of the LO relay belonging to such signal when the signal mechanism is in a proceed position selects a 75 or a 120 code, as the case may be, for transmission to the next signal in the rear in preference to a 180 code. For example, the deenergized condition of the light-out relay 4LO (see Fig. 2B) because of the lamp of signal 4 being burned out, when the mechanism is in a proceed position, causes the relay 5CP to be active for the transmission of a 120 code in the section 2—5T rather than a 180 code, irrespective of the energized condition of relay 4YGP. The circuit by which relay 5CP would be active under such conditions extends from (+), including contacts 104 and 105 of the mechanism of signal 5 in its danger position, contact 52 of oscillator 120C, back contact 107 of relay 4LO, front contact 108 of relay 4YGP, back contact 54 of relay 5H, winding of relay 5CP, and back contact 55 of relay 5TR, to (—).

20 The utility of the light-out relay control of code transmission to the signal in the rear in connection with approach lighting is dependent upon the manner in which the approach lighting becomes effective. That is, approach lighting for a given signal must be effective before a train has passed the next signal in the rear in order that the control of track circuit 25 code by the light-out relay for such given signal may be effective to restrict the signal in the rear before that signal is passed by the train.

30 According to the present invention, the approach lighting becomes effective as soon as a route is established for the signals included in the route, thus providing that the restricting of the rate of code transmission by a light-out relay will be effective to restrict the indication of the next signal in the rear prior to the passage 35 of such signal by a train proceeding over the route.

40 *Indications.*—In order that an operator at the control office can be well informed as to the movement of trains and the conditions of apparatus in the field, certain indicator lamps are provided on the control panel of the control machine at the control office. Some of such lamps are illustrated in Fig. 1 as being spaced along a track diagram corresponding to the trackway in the field at points comparable to track sections in the field with which such lamps are associated. Of such lamps, the lamps 2—3TE and 8—9TE indicate occupancy of the 45 OS track sections associated with the track switches 2W and 3W at field stations No. 2 and No. 3 respectively, the lamps 3TE and 8—11TE are for indicating occupancy of the siding sections belonging to the passing sidings A and B respectively, and the lamps 3ATE and 8ATE indicate occupancy of the end sections of the 50 stretch of track between the sidings A and B.

55 In addition to the lamps provided along the portion of the diagram corresponding to the trackway, traffic direction indicator lamps RFTE and LFTE are associated with traffic direction arrows for indicating east and west traffic directions respectively. The indicator lamps belonging to the traffic direction arrows also provide 60 an operator with information other than traffic

direction indications as will be apparent as the description progresses.

In addition to the above indicator lamps, an indicator lamp is associated with each of the switch and signal control levers. The lamps for the switch control levers SML have not been shown, but it is to be understood such lamps are provided in accordance with the usual practice. The signal indicator lamps 2-3GE and 8-9GE are associated with the signal control levers 2-3SGL and 8-9SGL respectively.

Each of the indicator lamps has for its control a magnetic stick relay which has its contacts maintained in a position corresponding to the last polarity of energization of the relay. This is in accordance with the organization generally employed in code communication systems, but it is to be understood that other types of relays could be employed if desired. Each of the magnetic stick relays TK is identified as being governed by a particular contact in the field as illustrated in Fig. 5 by similar wire reference characters, and it is to be understood that such relay can be controlled by direct wire from such contact, or through the medium of a code communication system, such, for example, as the system disclosed in the Judge et al. patent, No. 2,082,544, dated June 1, 1937.

The indicator lamps are dark under normal conditions. Upon the establishment of a route, the traffic direction indicator lamp RFTE or LFTE becomes illuminated in accordance with the traffic direction established, the illumination of such lamp being effective in accordance with the completion of the tumble-down of the code transmitters to provide for opposing signal protection.

As a specific example of the mode of operation of the system with respect to the control of the indicator lamps, it will be assumed that a route is established as has been described for eastbound traffic by the clearing of the head-block signal 2A at the right-hand end of the passing siding A. The dropping away of the relay 2RGP (see Figs. 2A and 5) in accordance with the clearing of that signal establishes a circuit at back contact 195 to apply energy to the wire 29 for the energization of the relay 2-3GK (see Fig. 1) at the control office with a polarity for operating the polar contact of such relay to its right-hand position. The closure of contact 196 of relay 2-3GK in its right-hand position causes the energization of the signal indicator lamp 2-3GE in an obvious manner.

When the tumble-down of the code transmitters for transmitting codes from left to right in the respective track sections of the stretch of track between the passing sidings A and B has become complete, the dropping away of the relay 9H for the right-hand end of the track section 6-9T opens the pick-up circuit for the traffic direction indication relay RFS (see Fig. 5) at field station No. 3 at front contact 197, and the slow action of the relay 9HP which has its circuit opened at front contact 198 of relay 9H delays the closure of a stick circuit for relay RFS at back contact 199 long enough to insure the dropping away of the relay RFS. In accordance with the dropping away of relay RFS, the closure of back contact 200 applies energy to wire 26 of a polarity to cause the magnetic stick relay RFTK at the control office to operate its polar contact 201 to a right-hand position and close an obvious circuit for the energization of the lamp 75

RFTE in the traffic direction arrow for eastbound traffic.

When an eastbound train accepts the signal 2A and enters the OS section 2-3T, the dropping away of the relay 2-3TR at field station No. 2 closes back contact 202 (see Fig. 5) to apply energy to wire 21 of a polarity to cause the relay 2-3TK (see Fig. 1) to operate its polar contact 203 to a left-hand position and closes an obvious circuit for the energization of the OS indicator lamp 2-3TE. The restoration to stop of signal 2A when the train enters section 2-3T causes the picking up of relay 2RGP, and the picking up of such relay reverses the polarity applied to wire 29 at contact 195 to cause the signal indicator lamp 2-3GE to be extinguished by the opening of its circuit at contact 196 of relay 2-3GK.

The entrance of the train into the end section 2-5T causes sufficient current to flow in the winding of the series relay 2SR (see Fig. 2A) to cause such relay to be picked up by the energization of a circuit closed from the positive terminal of track battery 67 including the winding of the series relay 2SR, front contact 59 of relay 2CP, upper rail of track section 2-5T, the track rail shunt caused by the presence of the train, and lower rail of track section 2-5T, to the negative terminal of track battery 67. The relay 2CP is steadily energized to close such circuit in accordance with the deenergized condition of the OS track relay 2-3TR. The circuit by which the relay 2CP is steadily energized under such conditions extends from (+), including back contact 65 of relay 2-3TR, front contact 66 of relay 2AS, winding of relay 2CP, and back contact 61 of relay 2TR, to (-).

The picking up of relay 2SR causes the picking up of the slow acting repeater relay 2SRP upon the closure of front contact 204, and the picking up of that relay closes a circuit at front contact 205 (see Fig. 5) to apply energy to wire 22 of a polarity to cause the operation of the polar contact 206 of relay 3ATK (see Fig. 1) at the control office to its left-hand position for the energization of the indicator lamp 3ATE to indicate the presence of the train in the track section 2-5T.

As the eastbound train proceeds further so as to leave the section 2-3T unoccupied in the rear of the train, the picking up of the OS track relay 2-3TR shifts the polarity applied to wire 21 by contact 202 (see Fig. 5) for the control of relay 2-3TK (see Fig. 1) to cause the extinguishing of the lamp 2-3TE by the opening of contact 203 of relay 2-3TK in its left-hand position.

When the OS section 2-3T becomes unoccupied in the rear of the train, the relay 2CP (see Fig. 2A) becomes active for the transmission of a 75 code in the track section 2-5T as indicated in the diagram of Fig. 6C and as has been specifically described. The pulsing of contact 59 of relay 2CP in the circuit for the series relay 2SR causes such relay to follow the coding as long as the track section 2-5T is occupied, but the slow action of relay 2SRP is sufficient to cause that relay to be maintained steadily picked up, and thereby maintain the indicator lamp 3ATE at the control office steadily energized.

When the track section 2-5T becomes unoccupied in the rear of the train, the dropping away of the series repeater relay 2SRP shifts the polarity applied to wire 22 at contact 205 (see Fig. 5) for the control of relay 3ATK (see Fig. 1) to cause the opening of the circuit for lamp 3ATE at polar contact 206 of relay 3ATK in its left-hand position. When the eastbound train occupies

the track section 4-7T as illustrated in Fig. 6D, and the track section 2-5T has become unoccupied in the rear of the train, an indication is provided that the train is present in an intermediate section by the traffic direction indicator lamp RFTE which is maintained energized. It will be noted that the lamp RFTE became illuminated when the route was established, together with the signal indicator lamp 2-3GE, but the signal indicator lamp 2-3GE was extinguished upon the entrance of the route by the train. A condition in which the traffic direction lamp RFTE is illuminated when the lamp 2-3GE is extinguished is indicative of occupancy of the stretch of track between the passing sidings A and B, such occupancy being effective to maintain the lamp RFTE energized because of the opposing signal protection provided by the de-energized condition of the relay 9H (see Figs. 2D and 5) for the right-hand end of track section 6-9T. Such organization of the system provides that means is provided for indicating the presence of a train in the stretch of track between the passing sidings, irrespective of the number of track sections involved, a distinctive indication being provided whenever either of the end sections 2-5T or 6-9T is occupied.

When an eastbound train advances to a position to occupy the track section 6-9T as illustrated in Fig. 6E, the increased flow of current through the series relay 9SR (see Fig. 2D) for the right-hand end of the track section is effective to cause such relay to follow the coding of relay 9CP which is active at that time, and by the pulsing of contact 207 to cause the relay 9SRP to be readily picked up. The picking up of relay 9SRP closes front contact 208 (see Fig. 5) to apply energy to wire 37 of a polarity to cause the operation of the polar contact 209 of relay 8ATK (see Fig. 1) to its right-hand position to close an obvious circuit for the indicator lamp 8ATE.

As the train progresses further so as to enter the OS section 8-9T, the dropping away of the relay 8-9TR causes the steady energization of the code transmitter relay 9CP (see Fig. 2D) by the energization of a circuit extending from (+), including back contact 131 of relay 8-9TR, front contact 132 of relay 9AS, winding of relay 9CP, and back contact 133 of relay 9TR, to (-). Because of such steady energization, the circuit for relay 9SR is maintained steadily closed at front contact 210 to maintain such relay energized until the track section 6-9T becomes unoccupied in the rear of the train. When the track section 6-9T becomes unoccupied in the rear of the train, the decreased flow of current in the track circuit causes the relays 9SR and 9SRP to be dropped away, and the dropping away of relay 9SRP shifts the polarity of the circuit for relay 8ATR to cause the opening of contact 209 (see Fig. 1) in its left-hand position to extinguish the lamp 8ATE. The occupancy of the OS section 8-9TR is indicated at the control office by the illumination of the lamp 8-9TE in a manner corresponding to that which has been described for the energization of the corresponding OS indicator for the track section 2-3T.

The entrance of the eastbound train into the track section 8-11T causes the dropping away of relay 8H (see Fig. 2D) and the dropping away of such relay closes a circuit at back contact 211 (see Fig. 5) to energize wire 39 with a polarity to cause the relay 8TK (see Fig. 1) at the control office to operate its polar contact 212 to a

right-hand position. The circuit for the indicator lamp 8-11TE, however, is dependent upon the communication of indications from the field that the H relays for both ends of the siding section 8-11T are deenergized. It has been pointed out when considering circuits for the clearing of signal 8A that the H relay for the right-hand end of the siding section 8-11T is dropped away when a route is established through such section for the passage of an eastbound train. Therefore a control has been communicated to the control office from field station No. 4 (not shown) at the right-hand end of the passing siding B to cause the energization of relay 11TK (see Fig. 1) with a polarity to operate its polar contact 213 to a left-hand position. Thus, the lamp 8-11TE is illuminated when the eastbound train enters the track section 8-9T by the energization of a circuit extending from (+), including polar contact 213 of relay 11TK in its left-hand position, polar contact 212 of relay 8TK in its right-hand position, and lamp 8-11TE, to (-).

When the track section 8-11T becomes unoccupied in the rear of the train, the picking up of the H relay at the right-hand end of the track section corresponding to the relay 3H of Fig. 2A is effective to cause the energization of the relay 11TK (see Fig. 1) at the control office with a polarity to operate its polar contact 213 to its right-hand position, and thereby open the circuit for the lamp 8-11TE. When the OS section 8-9T becomes unoccupied in the rear of the train, conditions are established as diagrammatically illustrated in Fig. 6F whereby the normal conditions of beat code transmission are restored for the track section 6-9T, thus providing for the energization of the relay 9H. In accordance therewith, the closure of front contact 191 of relay 9H (see Fig. 5) causes the picking up of the relay RFS by the energization of an obvious circuit, and the closure of front contact 198 of relay 9H causes the picking up of the relay 9HP, thus completing the restoration to normal conditions of the circuits for the relay RFS. The picking up of relay RFS closes a circuit at front contact 200 to apply energy to wire 36 for the energization of relay RFTK (see Fig. 1) at the control office with a polarity to cause the polar contact 201 of such relay to be operated to its left-hand position to open the circuit for the lamp RFTE belonging to the traffic direction arrow for eastbound traffic.

It will be noted that in the establishment of a route, it is the RFS or LFS relay for the exit end of the stretch of track involved that is dropped away for governing the traffic direction indication at the control office, the traffic direction relay for the entrance end of the route being maintained picked up throughout the movement of the train. Thus, for example, upon passage of the eastbound train as it has been described, the closure of back contact 214 of relay 2-3TR when the train accepts the head-block signal 2A applies energy to an obvious stick circuit for relay LFS to maintain such relay picked up. When the train enters the end section 2-5T, the dropping away of relay 2H causes the dropping away of relay 2HP by opening front contact 215, and the closure of back contact 216 of relay 2HP provides stick circuit energy for the relay LFS. The front contact 217 of relay 2SRP is effective to apply energy to the stick circuit for relay LFS as soon as the track section 2-5T becomes occupied by the train to insure the sustained energization

of the relay LFS upon passage of a short train in case the relay 2-3TR for the OS section should be picked up before the relay 2HP has had time to drop away. The picking up of relay 2H prior to relay 2HP upon restoration of beat code in the rear of a train causes the relay LFTE to be maintained picked up.

From the conditions which have been described it will be noted that the dropping away of a traffic direction relay RFS or LFS is dependent upon the tumble-down of the H relays in the stretch of track between the passing sidings. Therefore, if there is a tumble-down in both directions as in the case of the movement of a train out of an outlying switch as illustrated in Figs. 6J and 6K, the relays LFS and RFS for the respective ends of the stretch of track between the passing sidings A and B are both deenergized, and the lamps LFTE and RFTE (see Fig. 1) are both illuminated. The contemporaneous illumination of these lamps provides a distinctive indication for the operator at the control office that a train has entered the stretch of track from an outlying switch. Under such conditions, the relays LFS and RFS are restored to their normally energized conditions when the H relays with which they are associated are restored to normal after passage of the train.

Modifications.—It is to be understood that the circuits shown and described can be used as typical by those skilled in the art in adapting the system to conditions encountered in practice, certain features and principles being adaptable as sub-combinations to other types of coded track circuit signaling systems. The forming of beat codes, for example, for transmission of signal controls through the track rails could be applied to other signaling systems such as APB systems.

It may be desirable under certain conditions, such as in the case of grades and curves, to employ staggered intermediate signals rather than double intermediate signals. To adapt the circuits herein disclosed for a double intermediate signal location to a staggered intermediate signal location involves little change and can be accomplished, generally speaking, by simply eliminating one of the signals from the double location together with its directional stick relay S. The CP relay at the signal location ordinarily having its code selected by the relay YGP for the signal eliminated would have its code selected by a contact of the relay D for the adjoining end of the adjacent track section.

Although the preferred form of the invention is shown in Figs. 2A-2D, it is to be understood that in accordance with the scope of the beat code principle of the present invention, Figs. 2A-2D may be simplified by the omission of the back contact check of the track relays, such as the omission of back contacts 61, 55, 124, and so forth. This has been typically illustrated in Fig. 8 of the accompanying drawings which shows a portion of Figs. 2A and 2B.

It is believed to be unnecessary to point out the detailed operations of this modified form of the invention shown in Fig. 8, inasmuch as such operation is in general the same as above described in connection with the preferred form. It should, however, be noted that the transmitting relays 2CP and 5CP follow their coding contacts when connected to them, and because of this the beat codes are formed as a resultant of the combined application of energy at the opposite ends of the track section. It is, of course, obvious that when there is no energy applied at

one end by the transmitting relay 2CP, for example, then the transmitting relay 5CP can apply energy to actuate the relay 2TR. The same is of course true for the opposite direction. But when both of the transmitter relays 2CP and 5CP are energized and connect their respective batteries 67 and 57 to the track rails of the track section 2-5T, the result is the absence of current flow because the batteries oppose each other. Incidentally, if the batteries were so connected as to cause current flow, such current could not pass through either track relay because they are both disconnected from the track rails under such circumstances.

Certain relationships under normal beat code conditions of the system of Fig. 8, have been shown in the diagrams of Fig. 9. It should be understood, however, that these diagrams of Fig. 9 do not illustrate all of the conditions, as the character of the beat codes may vary slightly as one oscillator leads the other at varying degrees to produce relative conditions not illustrated. Inasmuch as the variations in phase between the different oscillators may be very numerous, no attempt has been made to illustrate such variations.

Although the form of the invention shown in Fig. 8 is entirely operative, it does not have the positive operating characteristics of the preferred form. The difference between the two forms will be observed by comparing Figs. 7 and 9. In Fig. 9 it is seen that some of the beat code impulses are of very short duration and although they may operate their respective track relays momentarily, such operation may have no substantial effect on the decoding apparatus. It will also be noted that the beat code pulses in Fig. 9 do not occur alternately in a regular fashion as they do in Fig. 7, but rather there are more impulses in one direction than there are in the opposite direction, thus tending to reduce the efficiency of transmission for one direction.

Thus, it can be seen that the beat code principle of operation may be applied to coded track circuit signaling systems in either of two ways, both of which are operative to provide tumble-down control in both directions, but the preferred form being found in practice to be more positive and efficient in its operation.

Inasmuch as the system is symmetrical in its organization for both directions of traffic in both forms of the invention, the conditions specifically described for one direction of traffic are to be considered as typical of conditions effective under similar traffic conditions for the opposite direction of traffic.

Having described a coded track circuit signaling system for a particular portion of trackway as one specific embodiment of the present invention, it is desired to be understood that this form is selected to facilitate in the disclosure of the invention rather than to limit the number of forms which the invention may assume, and it is to be further understood that various adaptations, alterations and modifications may be applied to the specific form shown to meet the requirements of practice without in any manner departing from the spirit or scope of the present invention except as limited by the appended claims.

What I claim is:

1. In a coded track circuit signaling system for railroads, a track section, a code following track relay and a source of current associated with each end of said track section, a code transmit-

ting relay for each end of said track section operable to connect the corresponding source of current across the track rails of said track section, coding contacts for the opposite ends of said track section intermittently operated at different code rates, and means including said coding contacts for operating said transmitter relays at the opposite ends of said track section at different time intervals, whereby both of said track relays are intermittently energized.

2. In a coded track circuit signaling system for railroads; a track section; a code following track relay and a source of current associated with each end of the track section; coding contacts operating intermittently at each end of the track section; code transmitting means for each end of the track section governed by the corresponding coding contacts to alternately connect said source of current and said track relay for that end intermittently across the rails for the respective transmission and reception of code impulses, said coding contacts at the opposite ends of said section operating at predetermined different rates so as to provide code pulses at relatively frequent intervals alternately in opposite directions in said track section, whereby the track relays at both ends are intermittently operated, and signaling means for each end of the track section responsive to the intermittent operation of the track relay belonging to that end.

3. In a coded track circuit signaling system for railroads, a track section, a code following track relay and a source of current associated with each end of the track section, code transmitting means at each end of the track section normally operating to connect the source of energy and the track relay for that end alternately across the track rails of the section at a predetermined rate for the respective transmission and reception of code impulses, said transmitting means for the opposite ends of said section operating at substantially different predetermined rates, whereby said track relays are both operated at recurrent intervals determined by the relationship between the different code rates for the opposite ends of the section, and decoding means at each end of said track section energized in response to the intermittent energization of corresponding track relay irrespective of the particular intervals of such energization.

4. In a coded track circuit signaling system for railroads; a track section; a code following track relay and a source of current associated with each end of the track section; coding contacts at each end of the track section operating at substantially different rates; code transmitting means at each end of the track section governed by said coding contacts for its end to alternately connect said source of current and said track relay for that end across the track rails, such transmitting means being effective to connect its source across said rails only provided the associated track relay is then deenergized, whereby the track relays for the opposite ends of said track section are both intermittently operated, and signaling means for each end of said track section, responsive to the intermittent operation of the corresponding track relay.

5. In a coded track circuit signaling system for railroads; a track section; a code following track relay and a source of current associated with each end of the track section; coding contacts at each end of the track section normally active to measure "on" and "off" periods at substantially different rates for the opposite ends of said sec-

tion, a code transmitter relay for each end of the track section governed by the associated coding contacts to alternately connect said source of current and said track relay for that end across the track rails, each of said transmitter relays being effective to connect its associated source of current across the rails only if the track relay for that end is deenergized, whereby the track relays for the opposite ends of said

10 track section are both intermittently operated, and the energization of a track relay at either end is maintained independently of the operation of its associated coding contacts throughout the pulse transmitted from that other end.

15 6. In a coded track circuit signaling system for railroads, the combination with a track section, a code following track relay and a source of current for each end of said track section, a transmitter relay for each end of said track section 20 acting when energized and deenergized respectively to connect said source of current and said track relay alternately across the track rails, coding contacts at opposite ends of said track section operating intermittently at different code rates, and an energizing circuit for each transmitter relay governed by the corresponding coding contacts and a back contact of the corresponding track relay, whereby each transmitter relay may be energized by the closure of its associated coding contacts only if the associated track relay is then deenergized.

7. In a coded track circuit signaling system for railroads, the combination with a stretch of track divided into a plurality of track sections, a code 35 following track relay and a source of current for each end of each track section, code transmitting means associated with each end of each track section and including intermittently operated coding contacts for connecting the corresponding source of current and track relay alternately across the track rails, said code transmitting means for the opposite ends of the same track section being normally controlled by coding contacts operating at different code rates and 40 thereby causing intermittent energization of both the track relays of that track section, and means associated with each track relay except those for the extreme ends of said stretch and responsive to the cessation of the coding operation of that track relay for automatically stopping operation of the code transmitting means for the adjoining end of the adjoining track section.

8. In a coded track circuit signaling system for a stretch of track divided into a plurality of track sections and having signals governing train movement in opposite directions, means comprising a code following track relay, a code transmitter relay and intermittently operated coding contacts for each end of each track section, said 55 code transmitter relays for opposite ends of the same track section being normally operated by the corresponding coding contacts to energize the track rails at different intervals and thereby cause intermittent operation of both track relays of that track section, means responsive to cessation of the coding operation of each track relay except those for the extreme ends of said stretch for stopping the operation of the code transmitter relay for the adjoining end of the 60 adjacent track section, and signal control means for governing the indications of each signal in response to the coding operation of the associated track relay in absence of opposing code pulses.

9. In a coded track circuit signaling system for railroads, a stretch of single track having a head-

block signal at each end governing train movement into the stretch, driven code transmitting means at opposite ends of the stretch including intermittently operated coding contacts and normally active to apply impulses to the track rails at different intervals to provide beat code pulses transmitted through the track rails in opposite directions, and signal control means manually controlled from a distant control office and effective only if code pulses are being received through the track rails from the opposite end for governing the clearing of a head-block signal at either selected end of the stretch and stop operation of the corresponding code transmitting means to prevent clearing of the opposing signal.

10. In a coded track circuit signaling system for a stretch of track divided into a plurality of track sections and having signals at intervals for governing train movement in opposite directions, code transmitting means including a code transmitter relay and coding contacts associated with each end of each track section, said code transmitter relays for the opposite ends of the same track section being normally operated at different intervals by their coding contacts to provide code pulses at intervals in opposite directions over the track rails of that track section and thereby intermittently energize both the track relays of that track section, code responsive means associated with each end of each track section acting in response to the cessation of pulses transmitted toward that end to stop operation of code transmitting means for the adjacent end of the adjoining track section, means for governing the indications of each of said signals in accordance with the rate of the code pulses being received at that signal in the absence of any opposing code pulses, and means manually controlled from a distant control office for rendering ineffective the code transmitting means at either selected end of the stretch only if code pulses are then being received at that end, whereby manual control may be exercised only if the stretch is not occupied to clear the signals for either desired direction of train movement through the stretch and put to stop the opposing signals.

11. In a coded track circuit signaling system for single track railroads, a stretch of single track divided into a plurality of track sections and having normally at stop head-block signals at the opposite ends of said stretch for governing train movement into the stretch in both directions, code receiving means including a code following track relay and associated with each end of each of the track sections, driven code transmitting means associated with each end of each of the track sections and normally effective to intermittently energize the track rails of its section only if the code receiving means for the adjoining track section is receiving means for the adjoining track section is receiving code pulses, said driven code transmitting means for the opposite ends of the same section acting to apply impulses to the track rails at different intervals and thereby cause operation of both track relays of that track section, signal control means associated with each head-block signal for rendering the associated driven code transmitting means inactive and causing that signal to indicate proceed only provided its associated code receiving means is receiving a driven code, and manually controlled means for governing said signal control means, whereby the manual clearing of a head-block signal at one

end of the stretch causes a cessation of the driven code from that end of the stretch and in each of the succeeding track sections and thereby prevents the clearing of the opposing signal in response to manual control of its signal control means.

12. In a coded track circuit signaling system for railroads for a stretch of track divided into a plurality of track sections, a signal normally at stop at each end of the stretch for governing train movements into the stretch, coding contacts at each end of each track section in the stretch, driven code transmitting means at the opposite ends of each track section governed by the corresponding coding contacts to intermittently energize the track rails of such section, said coding contacts for opposite ends of that section operating at substantially different rates, means associated with each of said transmitting means, except those at the ends of the stretch, for rendering it active only if code pulses are being received over the track rails of the adjacent section from the opposite end of that adjacent section, means manually controlled from a distant control office for clearing either selected one of said signals if a code is being received over the track rails in advance of such signal, and means at each end of said stretch for rendering the code transmitting means at that end inactive when the corresponding signal is cleared.
13. In a coded track circuit signaling system for a stretch of track having a signal at each end governing train movements into the stretch; a track relay at each end of said stretch, code transmitting means at the opposite ends of the stretch and governed by the associated track relay for normally transmitting pulses alternately in opposite directions over the track rails of the stretch, such code transmitting means being effective to transmit code pulses at a particular distinctive rate only if no pulses are being transmitted by the code transmitting means for the opposite end of the stretch; means manually controlled from a distant control office for rendering the code transmitting means inactive at either selected end of said stretch without causing the cessation of the transmitting means for the opposite end, and signal control means for causing each signal to indicate clear only if a code at said particular rate is being transmitted through the track rails by the code transmitting means at the opposite end of such stretch.
14. In a coded track circuit signaling system for a stretch of track divided into a plurality of track sections and having signals at intervals governing train movement into and through said stretch in opposite directions, a code following track relay and a source of current for each end of each track section, code transmitting means associated with each end of each track section and including intermittently operated coding contacts for connecting the corresponding source of current and the track relay alternately across the track rails, said code transmitting means for the opposite ends of the same track section being normally controlled by coding contacts operated at different code rates and thereby causing intermittent energization of both of the track relays of that track section, code responsive means associated with each track relay except those for the extreme ends of the stretch and effective upon cessation of the coding operation of that track relay to

render ineffective the code transmitting means for the adjoining end of the adjacent track section, means for stopping transmission of code pulses in either end track section toward the other end of said stretch and thereby stop transmission of pulses in the same direction in successive track sections, and decoding means associated with each signal for governing the clear and caution indications thereof in accordance with the rate of coding operation of the associated track relay existing when the opposing code is removed.

15. In a coded track circuit signaling system of the character described, a track section having signals at each end governing train movement into and out of said track section, a code following track relay and a code transmitter relay for each end of said track section, coding contacts for each end of said track section intermittently operated at different code rates, code responsive means associated with each track relay and energized only by the coding operation of that track relay, each of said code responsive means when energized acting to connect the corresponding transmitter relay to particular coding contacts and when deenergized to coding contacts operating at different rates and selected in accordance with the indications of the associated signal governing train movement out of said track section, said particular coding contacts at opposite ends of said track section operating at different rates and thereby normally causing energization of said decoding means at both ends of said track section, and means for rendering ineffective the code transmitter relay for either end of said track section and thereby permit control of the caution and clear indications of the associated signal in accordance with the code rate being transmitted without interference by the other code transmitter relay.

16. In a coded track circuit signaling system for a stretch of track divided into a plurality of track sections and having color-light signals at intervals governing train movement through said stretch in opposite directions, a code following track relay for each end of each track section, code transmitting means associated with each end of each track section and including intermittently operated coding contacts for applying code pulses to the track rails, said code transmitting means for the opposite ends of the same track section being governed by coding contacts operating at different code rates to provide code pulses at different intervals to energize intermittently both of the track relays of said track section, code responsive means associated with each track relay and energized only by the coding operation of that track relay, each of said code responsive means except at the extreme ends of said stretch acting when deenergized to render ineffective the code transmitting means for the adjoining end of the adjacent track section, means for lighting each of said signals upon deenergization of the code responsive means for either of the corresponding ends of the adjacent track section, and means for governing the transmission of code pulses in each end track section toward the other end of the stretch.

17. In a coded track circuit signaling system for a stretch of track divided into a plurality of track sections and having signals at the ends of said track sections governing train movement in the opposite directions, a code following track relay for each end of each track section, code

transmitting means including intermittently operated code contacts associated with each end of each track section, said code transmitting means for the opposite ends of the same track section normally acting to transmit pulses at intervals in opposite directions over the track rails of that track section to cause intermittent energization of both of the track relays of that track section, code responsive means for each track relay energized by its coding operation, said code responsive means for each track relay except those for the extreme ends of the stretch acting when deenergized to render ineffective the code transmitting means for the adjoining end of the adjacent track section, each of said code responsive means acting when deenergized to render the associated code transmitting means responsive to the operation of coding contacts operating at different rates and selected in accordance with the presence or absence of a train in an adjacent track section, and decoding means responsive to the rate of the coding operation of each track relay in the absence of opposing pulses for governing the caution or clear indications of the corresponding signal.

18. In a coded track circuit signaling system for railroads for a stretch of track divided into a plurality of track sections having signals for governing traffic in both directions through the respective sections; code transmitting means including coding contacts at each end of each of the track sections operative to transmit impulses through the track rails to the opposite end of that track section, said code transmitting means for the opposite ends of the same track sections being normally controlled by coding contacts operating at different rates, each of said transmitting means being effective to transmit at a particular distinctive rate if the adjacent track section is not occupied and the code transmitting means for the opposite end of that particular track section is inactive; means associated with each of said transmitting means, except those for the extreme ends of said stretch, for rendering it active only if code pulses are being received over the rails of the adjacent section from the opposite end of that adjacent section, means manually controlled from a distant control office for causing the signal governing entrance to said stretch at either selected end to indicate caution if a code is received over the track rails in advance thereof, and to indicate clear only if a code at said particular rate is received over the track rails in advance thereof; and means at each end of said stretch for rendering the code transmitting means at that end inactive when the corresponding signal indicates caution or clear.

19. In a coded track circuit signaling system for a stretch of single track between the ends of passing sidings divided into a plurality of track sections and having signals at intervals governing train movement in opposite directions into and through said stretch, a code following track relay for each end of each track section, code transmitting means for the opposite ends of each track section including intermittently operated contacts for normally transmitting beat code pulses at different intervals in opposite directions over the track rails of that track section and thereby energize intermittently both of the track relays of that track section, manually controlled means for stopping transmission of code pulses over the track rails of the successive track sections in either selected direction and

permit transmission of code pulses without interference in the other direction for governing the indication of the signals for one direction of train movement while holding at stop the opposing signals, and directionally controlled means associated with each intermediate signal in the stretch and responsive only to the movement of a train in the direction of traffic governed by that signal for providing code pulses for clearing signals in the rear for following train movements.

20. In a coded track circuit signaling system for a stretch of single track between the ends of passing sidings divided into a plurality of track sections and having signals governing train movement in opposite directions into and through said stretch, one of said track sections including an outlying track switch, a code following track relay for each end of each track section, code transmitting means for the opposite ends of each track section including intermittently operated coding contacts for normally transmitting pulses at intervals in opposite directions over the track rails of that track section to energize intermittently both track relays of that track section, code responsive means responsive to the cessation of the coding operation of each track relay except those for the extreme ends of said stretch for rendering ineffective the code transmitting means for the adjoining end of the adjacent track section, and decoding means governing the clear indications of each signal and responsive to the coding operation of the associated track relay in the absence of opposing code pulses, said code responsive means acting upon the entrance of a train into the stretch from said outlying switch to put to stop the signals governing train movement in both directions toward that switch and permit the signals governing train movement from said switch toward either end of the stretch to be controlled by code pulses without the interference of opposing code pulses.

21. In a coded track circuit signaling system for a stretch of track having a signal at each end governing train movement into the stretch, a code following track relay at each end of said stretch, code transmitting means including intermittently operated coding contacts for the opposite ends of said stretch and normally acting to provide beat code pulses at intervals in opposite directions and thereby energize intermittently both of said track relays, manually controlled means for governing the clearing of each of said signals subject to the reception of code pulses at the corresponding end of said stretch, means effective when the signal at either end of said stretch is cleared for stopping transmission of code pulses toward the other end of said stretch, and means associated with each of said signals and acting when that signal has once been cleared for preventing transmission of code pulses from the corresponding end of said stretch for an interval of time after that signal is manually put to stop.

22. In a coded track circuit signaling system for a stretch of single track divided into a plurality of track sections and having signals at the entrances to said track sections for governing train movement into opposite directions, a code following track relay for each end of each track section, code transmitting means for each end of each track section including contacts operable at distinctive clear and caution code rates, a home relay energized by the intermittent operation of each track relay regardless of the rate

of such operation, a distant relay for each signal energized only if the corresponding track relay is operated at a clear code rate, directional means associated with each intermediate signal and energized while the track section in advance

5 of that signal is occupied by a train making a movement in the direction of traffic governed by that signal, each home relay when energized rendering the corresponding code transmitting means operable at the caution code rate providing, except in the case of the home relays for the extreme ends of the stretch, that the home relay for the adjoining end of the adjacent track section is also energized, said caution rates for the 10 opposite ends of the same track section being different to provide current pulses in both directions and cause energization of both track relays and their corresponding home relays for that track section, each of said home relays except those for the extreme ends of the stretch acting 15 when deenergized to govern the associated code transmitting means by coding contacts operating at the clear and caution code rates if the home relay for the adjacent end of the adjoining track section is energized or the corresponding directional means is energized respectively, and means manually controlled from a distant control office for rendering ineffective said code transmitting means at either selected end of the 20 stretch only if the home relay at that end is then energized.

23. In a coded track circuit signaling system for railroads, in combination with a track section, a code following track relay and a source of current for each end of each track section, a transmitter relay at each end of said track section operable to connect said source of current and said track relay alternately across the track rails, coding contacts at opposite ends of said 25 track section operating at different code rates and normally acting to govern both of said transmitter relays and thereby cause intermittent energization of both of said track relays, and means for rendering said transmitter relay at one end of said track section ineffective at 30 times and thereby permit energization of the associated track relay without interference at a code rate determined by the other transmitter relay.

24. In a coded track circuit signaling system for railroads, the combination with a track section having a signal at one end governing train movement into the track section, a code following track relay and a source of current for each 35 end of said track section, code transmitting means for each end of said track section including a transmitter relay and coding contacts intermittently operated, said transmitter relays for the opposite ends of said track section being normally operated by coding contacts operating at different rates to connect said source of current and said track relays to the track rails at different intervals and thereby cause intermittent operation of both of said track relays, decoding means for governing the indication of said 40 signal and responsive to the rate of the coding operation of the corresponding track relay, and means for rendering said transmitter relay at said signal ineffective and thereby permit coding operation of the associated track relay without interference at a rate determined by the other transmitter relay.

25. In a coded track circuit signaling system for railroads for a stretch of track divided into track sections and having light signals for gov-

erning traffic in both directions through each of the track sections; code transmitting means at each end of each of the track sections normally active to transmit impulses through the track rails to the opposite end of that track section, said code transmitting means except those for the extreme ends of the stretch, being dependent upon the reception of a code in the adjacent section through the track rails from the opposite end of that adjacent section, means manually controlled from a distant control office for rendering said code transmitting means inactive at either selected end of said stretch of track; means associated with each of the light signals for causing its illumination in response to the cessation of code transmission in the track section in the rear; signal control means for each of the signals for causing such signal to indicate clear if a particular code is transmitted to such signal through the track rails of the track section immediately in advance thereof, and means for each signal effective only if that signal is lighted for permitting the code transmitting means for the section next in the rear to provide said particular code.

26. In a coded track circuit signaling system for a stretch of track including a power-operated track switch, a home signal and a distant signal governing train movement over said switch in one direction, means associated with the opposite ends of the track section between said signals and each including coding contacts operated at different code rates normally acting to provide code pulses in both directions at different intervals over the track rails of said track section, approach locking means governed by the code pulses received at the home signal for preventing power operation of said track switch, and means responsive to the presence of a train approaching said distant signal for preventing transmission of code pulses toward said home signal, thereby controlling the approach locking and permitting transmission of code pulses without interference by opposing code pulses toward said distant signal for governing its indications.

27. In a coded track circuit signaling system for railroads for a stretch of track having first and second signals normally at stop at the ends of said stretch for governing traffic in the same direction, the first signal governing train movement out of the stretch over a power operated track switch and second signal governing entrance to such stretch, track circuit code transmitting means including intermittently operated coding contacts at each end of said stretch, said coding contacts normally operating at different rates to transmit impulses over the track rails alternately in opposite directions, means manually controlled for clearing said second signal if a code is transmitted through the track rails from the opposite end of the stretch, such manual clearing of the second signal being effective to render ineffective the code transmitting means for that end of the stretch, normally energized approach locking stick relay for said switch associated with said first signal, means for deenergizing said approach locking relay when said first signal is cleared, and for reenergizing said approach locking stick relay when said first signal is restored to stop immediately only if a code is transmitted through the track rails from the opposite end of the stretch, but only after an interval of delay if no code is being transmitted, whereby the reenergization of the approach locking relay associated with said first signal can be effected immediately upon the restoration of such first

signal to stop only if said second signal is also at stop.

28. In a coded track circuit signaling system for railroads, a stretch of track, code transmitting means at opposite ends of said stretch normally active to transmit driven code pulses through the track rails at intervals in both directions, means manually controlled from a distant control office for rendering said code transmitting means inactive at either selected end of said stretch without stopping transmission of code pulses from the opposite end, an indicator lamp at the control office for each direction of code transmission through the track rails of said stretch, and circuit means responsive to the cessation of code transmission through the track rails of said stretch in either direction for energizing the corresponding indicator lamp.

29. In a coded track circuit signaling system for railroads for a stretch of track divided into track sections; code transmitting means including intermittently operated coding contacts at each end of each of the track sections, said code transmitting means for the opposite ends of the same track section being normally controlled by coding contacts operated at different rates to provide code pulses at intervals in both directions, means at each of the adjacent ends of the track sections for rendering said code transmitting means active at such end only if code pulses are being received at the adjoining end of the adjacent track section, means manually controlled from a distant control office for rendering said code transmitting means inactive at either selected end of said stretch of track, an indicator lamp at the control office for each direction of code transmission through the track rails of said stretch; and circuit means for causing the energization of each of the indicator lamps in response to the cessation of the code transmitting means for all of the track sections for a corresponding direction of code transmission.

30. In a coded track circuit signaling system for a stretch of track divided into a plurality of track sections, one of said track sections including an outlying switch, code transmitting means for the opposite ends of each of said track sections operating in response to the intermittent closure of coding contacts operating at different code rates to provide driven code pulses at intervals in both directions, means for rendering each of said code transmitting means except those for the extreme ends of said stretch inactive if no code pulses are being received at the adjoining end of the adjacent track section, two indicator lamps in the control office one for each direction of traffic, and means for lighting each of said indicator lamps in response to the cessation of coding in a corresponding direction, the shunting of a track section by train movement from said outlying switch acting to stop transmission of code pulses to the both ends of the associated track section and thereby causing lighting of both of the said indicator lamps.

31. In a coded track circuit signaling system for railroads; a stretch of track divided into a plurality of track sections one of which includes an outlying track switch; code transmitting means at opposite ends of each track section normally active to transmit driven code pulses through the track rails at intervals in both directions; means at each of the adjacent ends of the track sections for rendering said code transmitting means active at such end in accordance with the reception of code pulses in the

adjacent section through the track rails from the opposite end of that adjacent section; means manually controlled for rendering said code transmitting means inactive at either selected end of said stretch of track; an indicator lamp at the control office for each direction of traffic through said stretch of track; control circuit means for each of said indicator lamps for causing the energization of that lamp when the code transmission stops for the corresponding direction of traffic; whereby said lamps are selectively illuminated in accordance with the direction of traffic manually established; and whereby both of said indicator lamps are illuminated if a train enters said stretch from said outlying track switch.

32. In a coded track circuit signaling system for railroads for a stretch of track divided into track sections and having light signals for governing traffic in both directions through each of the track sections; code transmitting means at each end of each of the track sections including intermittently operated coding contacts and normally active to transmit impulses through the track rails alternately in opposite directions; means at each of the adjacent ends of the track sections for rendering said code transmitting means active at such end in accordance with the transmission in the adjacent section of a code through the track rails from the opposite end of that adjacent section, whereby the inactivity of the code transmitting means for one end of one track section renders the corresponding transmitting means for an adjacent track section inactive; means manually controlled from a distant control office for rendering said code transmitting means inactive at either selected end of said stretch of track; means associated with each of the light signals for causing its illumination in response to the cessation of code transmission through the track rails to such signal in either of the track sections adjacent that signal location; and signal control means for each of the signals for causing such signal to clear when a code is transmitted to such signal through the track section immediately in advance thereof in the absence of opposing code pulses.

33. In a coded track circuit signaling system, a stretch of single track divided into a plurality of track sections and having signals at intervals governing train movements into and through said stretch, a code following track relay for each end of each track section, code transmitting means for each end of each track section including coding contacts operating at different rate for the opposite ends for normally transmitting beat code pulses in opposite directions through such track section, manually controlled means for stopping the code transmission in either selected direction, decoding apparatus with each signal and governed by the corresponding code following track relay to clear that signal only providing no code is being transmitted toward said signal in the rear thereof, and means preventing the operation of each code transmitting means unless the corresponding signal indicates stop.

34. In a coded track circuit signaling system for railroads for a stretch of track divided into a plurality of track sections, a signal normally at stop at each end of each of the track sections for governing entrance to that section and having a mechanism operable to clear and stop positions, track circuit code transmitting means at

each end of each of the track sections normally active to intermittently energize the track rails, such code transmitting means at each of the adjacent ends of the adjacent sections being active only if the mechanism of the signal at such end governing entrance to the adjacent section is at stop, means at each of the adjacent ends of the track sections for rendering said code transmitting means active at such end in accordance with the reception in the adjacent section of a code through the track rails from the opposite end of that adjacent section, means manually controlled from a distant control office for rendering said code transmitting means inactive at either selected end of said stretch and thereby render the code transmitting means for the respective sections inactive for a selected direction of code transmission, and signal control means for each of the signals effective to operate the mechanism of such signal to a clear position only if the track rails in advance of that signal are intermittently energized by the transmitting means at the opposite end of the section, and only if said manual control means has been effective to stop the code transmission toward the other signal.

35. In a coded track circuit signaling system for railroads, a stretch of track, code transmitting means at the opposite ends of said stretch normally operating to transmit driven code pulses through the track rails at different intervals in both directions to form a beat code but each of said code transmitting means continuing to transmit its driven code pulses upon the cessation of the other transmitting means, decoding apparatus for each end of the stretch energized in response to the reception of either driven code pulses or beat code pulses, manually controlled means for rendering said code transmitting means inactive at either selected end of said stretch to thereby cause the deenergization of the decoding apparatus at the opposite end of the stretch, directionally controlled means associated with each decoding apparatus and distinctively responsive to the deenergization of its decoding apparatus when it is deenergized by reason of the stopping of the code transmission from the opposite end of the stretch but being unresponsive to its deenergization by the passage of a train into said stretch from its own end, and an indicator lamp associated with each of said directionally controlled means and controlled thereby so as to be illuminated only when its directionally controlled means is distinctively controlled.

36. In a coded track circuit signaling system for railroads, a stretch of track having head-block signals at the opposite ends for governing traffic into the stretch, code transmitting means at opposite ends of said stretch normally active to transmit driven code pulses through the track rails at intervals in both directions, decoding apparatus at each end of the stretch normally energized in response to the reception of code pulses from the opposite end of the stretch for controlling the indications of the head-block signal at the corresponding end, manually controlled means for rendering said code transmitting means inactive at either selected end at said stretch to thereby cause the deenergization of the decoding apparatus at the opposite end of the stretch, a stick relay associated with each decoding apparatus and having a pick-up circuit energized when its corresponding decoding apparatus is energized and having a stick circuit

energized when a train is approaching its associated head-block signal and then being maintained energized when the train passes said head-block signal by the deenergized condition of its block signal by the deenergized condition of its associated decoding means, whereby said stick relays are selectively deenergized in accordance with the direction of traffic established, and two indicator lamps, one for each direction of traffic, said lamps being respectively controlled by that one of said stick relays which is deenergized for the corresponding direction of traffic.

37. In a coded track circuit signaling system for railroads, a stretch of track, code transmitting means at each end of said stretch normally active to transmit impulses through the track rails to the opposite end thereof, track circuit code receiving means at each end of said stretch energized only in response to track circuit codes transmitted through the track rails from the opposite end of the stretch, means at each end of the stretch for communicating an indication of the energized or deenergized condition of said track circuit code receiving means at that end to a distant control office, and visual indicating means at the control office responsive only to the joint deenergized condition of the track circuit code receiving means at both ends of said stretch for providing a track occupancy indication.

38. In a coded track circuit signaling system for railroads for a stretch of track having end track sections and at least one intermediate section, code transmitting means at each end of each of the track sections normally active to transmit impulses through the track rails to the opposite end of that track section at different intervals, means at each of the adjacent ends of the track sections for rendering said code transmitting means active at such end in accordance with the transmission in the adjacent section of a code through the track rails from the opposite end of that adjacent section, means manually controlled from a distant control office for rendering said code transmitting means inactive at either selected end of said stretch and thereby causing the corresponding code transmitting means for each of the other track sections to become inactive, an indicator lamp at a distant control office for each of the end track sections, a direction indicator lamp at the control office for each direction of code transmission through the track rails of said stretch, means associated with said code transmitting means for each end of the stretch of track responsive to an increased flow of current in the associated track section because of the presence of the train in that section for causing the illumination of the indicator lamp at the control office for the corresponding end track section, and circuit means responsive to the cessation of code transmission through the track rails of the various track sections of said stretch in either direction for energizing the corresponding direction indicator lamp at the control office.

39. In a coded track circuit signaling system for railroads for a stretch of track having end track sections, code transmitting means at each end of each of the track sections normally active to transmit impulses through the track rails to the opposite end of that track section at different intervals, means at each of the adjacent ends of the track sections for rendering said code transmitting means active at such end in accordance with the transmission in the adjacent section of a code through the track rails

from the opposite end of that adjacent section, an indicator lamp for each of the end sections at a distant control office, and means associated with said code transmitting means for each end of the stretch of track responsive to an increased flow of current in the associated end track section because of the presence of a train in that track section for causing the illumination of the indicator lamp at the control office for the corresponding end track section.

40. In a coded track circuit signaling system for railroads, a stretch of track having normally-at-stop signals for governing traffic in both directions through such stretch, driven code transmitting means normally active to transmit driven code pulses at intervals in both directions through said stretch, such transmitting means at times being manually interrupted from a distant control office for either selected direction in accordance with a selected one of said signals desired to indicate clear, and code receiving means for each of said signals being responsive to a driven code transmitted through the track rails from the opposite end of the stretch to its signal to indicate clear only providing the code transmitting is manually prevented from transmitting a driven code for the opposite direction.

41. In a coded track circuit signaling system for a stretch of single track between the ends of passing sidings divided into a plurality of track sections, coding means for each end of said track sections including intermittently operated coding contacts and normally operating to send driven code pulses at intervals in both directions over the track rails of said track sections, means for rendering each of said coding means except those for the extreme ends of said stretch ineffective when no pulses are being received at the adjacent end of the adjoining track section, a head-block signal at each end of the stretch governing train movement into the stretch, means manually controlled from a distant control office for governing the clearing of said head-block signal for either selected end of the stretch, and means for each head-block signal including a stick relay and time element device and actuated when the associated signal has been cleared and for a predetermined time after it is subsequently put to stop manually for rendering the associated coding means ineffective to send code pulses toward the opposite end of the stretch.

42. In a coded track circuit signaling system for a stretch of single track between the ends of passing sidings including an end track section at each end of said stretch, coding means for each end of the stretch including a transmitter relay acting when energized to connect a source of current in series with a series relay across the track rails of said stretch, said series relay being energized during the operation of said transmitter relay by the increased flow of current due to the presence of a train in the corresponding end track section, means for each end track section including intermittently operated coding contacts for intermittently energizing the associated transmitter relay when the corresponding end track section is occupied by a train moving in either direction, occupancy indicating means in a distant control office, and means for governing said indicating means in accordance with the energized and deenergized condition of said series relays.

43. In a coded track circuit signaling system for a stretch of single track between the ends of passing sidings including an end track section

adjacent each siding end, a head-block signal at each end of the stretch governing train movement into the stretch, means manually controlled from a distant control office for selectively governing the clearing of said signals, code transmitting means for each end of the stretch including intermittently operated coding contacts and effective unless the associated signal is cleared by manual control for applying code pulses across the track rails of said stretch, said code transmitting means including a series relay energized each time a code pulse is applied if the corresponding end track section is then occupied by a train moving in either direction, and indicating means in said control office governed by said series relays for indicating occupancy of said end track sections.

44. In a coded track circuit signaling system for a stretch of single track divided into a plurality of track sections, one of said track sections including an outlying track switch, code responsive means for each end of said stretch, code sending means and code receiving means for said track sections normally cooperating when said stretch is not occupied by a train to send code pulses at intervals in opposite directions over the track rails of said track section and thereby cause energization of both of said code responsive means, means for rendering each of said code sending means except those for the extreme ends of said stretch inactive if the code receiving means for the adjacent end of the adjoining track section is deenergized, occupancy indicating means in a distant control office, and means acting over line wires connecting said control office with both ends of said stretch for rendering said indicating means effective to show occupancy of the stretch when both of said code responsive means are deenergized by the entrance

of a train into the stretch from said outlying switch.

45. In a coded track circuit signaling system for a stretch of track having a signal at each end governing train movement into said stretch, code responsive means for each end of said stretch, code transmitting means for the opposite ends of said stretch normally operated to send current pulses at intervals in both directions over the track rails of said stretch and thereby cause energization of both of said code responsive means, means manually controlled from a distant control office for selectively governing the clearing of said signals, indicating means in said control office for indicating occupancy of said stretch, and means governed over line wires connecting said control office at both ends of said stretch for rendering said indicating means active only when both of said code responsive means are deenergized.
46. In a coded track circuit signaling system for a stretch of single track, code responsive means for each end of said stretch, coding means manually controlled from a distant control office for normally transmitting current pulses over the track rails of said stretch at intervals in opposite directions and thereby energize both of said code responsive means, occupancy indicating means in said control office, control means responsive to the deenergization of either of said code responsive means for rendering said indicating means active until that code responsive means is again energized by current pulses, and means actuated by the entrance of a train into said stretch for maintaining said control means for the corresponding end of the stretch inactive while the associated code responsive means is deenergized by the presence of such train.

THOMAS J. JUDGE.
